UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

AUTOMATIC TELEPHONE SYSTEM.

Application filed December 14, 1923, Serial No. 680,596. Renewed August 26, 1927.

The present invention relates to automatic telephone systems in general, but is concerned more particularly with automatic telephone systems in which talking battery is supplied from a trunking switch (selector) rather than from a final switch (connector); and one object is the production of new and improved circuit arrangements whereby the inter-office trunk circuits in a multi-office system embodying the invention are accurately balanced to prevent cross-talk and other undesirable inductive defects, and are also grounded at one end only, so as to avoid the possibility of disturbances due to varying ground potentials.

Another object of the present invention is to provide circuit arrangements whereby an automatic telephone system of the above mentioned type may be interconnected with an existing manual telephone system, and also to provide circuit arrangements such that the requirements of both systems may be met when calls are being extended from automatic subscribers to manual subscribers, and vice versa. Another object is to simplify as much as possible, consistent with good operation, the circuits of the intermediate selectors and of the connectors.

There are a great many other objects and features of the invention which are more or less incidental to the objects set forth above and which will be brought out clearly hereinafter.

Although various features of the invention are applicable equally well to single office automatic telephone systems and to multi-office automatic telephone systems embracing any number of separate offices, it has been chosen to illustrate the present invention in connection with a large multi-office telephone system in which some of the offices are automatic and some are manual. It is assumed further that the offices are laid out in districts with not more than ten offices per district and not more than ten districts. Accordingly, the first numerical switch, which in this case is a first selector repeater, is operated to select a trunk line extending to an office selector (in this case an incoming selector repeater) in the desired district and this office selector responds to the second digit dialled to select the desired office.

Referring now to the accompanying drawings comprising Figs. 1-10, inclusive,

Figs. 1-9, inclusive, are circuit drawings and show diagrammatically a sufficient amount of apparatus in a telephone system embodying the principles of the invention to enable the invention to be understood, and Fig. 10 is a drawing layout showing how the sheets of drawings should be placed together.

Figs. 1-4, inclusive, show a sufficient amount of equipment for a complete connection between the line of substation A, Fig. 1, in one office and the line of substation A', Fig. 4, in another office. This connection is established automatically without the aid of an operator.

Figs. 5 and 6, when taken in connection with the remaining part of the drawings, show a sufficient amount of equipment for making connections between the manual subscriber at substation A² and any automatic subscriber.

Fig. 7 shows a so-called "zero" operator's cord circuit which may be taken into use when the digit 0 is dialled by any subscriber or by any "A" operator who is having difficulty in obtaining the desired connection. The zero operator may extend the connection either manually or automatically as she sees fit.

Fig. 8 shows a toll recording operator's key circuit by means of which she answers calls extended to her position.

Fig. 9 shows a "B" operator's cord circuit by means of which she completes connections to manual subscribers, such as the one at A³, when the trunk associated with the cord circuit is seized by an automatic switch under the control of an automatic subscriber or a calling operator who desires to extend a connection to a manual line.

The line switch C, Fig. 1, is mechanically of the well known rotary type in which the wipers have no normal position and are moved in a forward direction only. This line switch is employed for the purpose of connecting the associated line, when calling, with an idle first selector.

The first selector repeater D, Fig. 1, which in this case functions as a district selector, is mechanically of the well known vertical and rotary type of switch, having its bank contacts arranged in horizontal rows or levels. This selector is arranged to supply talking battery to the calling subscriber and to repeat the interruptions produced by the

calling subscriber's calling device after it has selected an idle trunk. This switch is also arranged to feed battery forward in the direction of the called subscriber when the 5 "switch-over" operation occurs after the last digit in the number has been dialled.

The incoming selector repeater E, Fig. 2, which functions as an office selector, is mechanically identical with the first selector 10 repeater D, Fig. 1. Its circuits, however, differ somewhat from those of the latter switch, owing to the different requirements which the former meets, as will hereinafter appear.

15 The selector D', Fig. 6, is also an incoming selector repeater and is identical with the incoming selector repeater E, Fig. 2. The selector D', however, functions as a district selector like the first selector repeater D, Fig. 1, and not as an office selector.

20 The thousands selector F, Fig. 3, is identical mechanically with the switches mentioned above, but is somewhat simpler from the circuit standpoint, owing to the fact 25 that it has no repeating actions to perform. The hundreds selector G is identical with the selector F.

25 The connector H is mechanically a vertical and rotary switch similar to the selectors, 30 but its circuits are arranged so that the shaft is operated in both its movements under the directive control of the calling subscriber. This connector responds to the interruptions produced in the circuit of its 35 line relay until it is completely operated, after which the incoming trunk conductors are extended straight through to the wipers and the line relay is cut off.

40 The various operator circuits shown in the drawings are more or less modifications of existing circuits, having the new features to be explained fully hereinafter.

45 The system having been described generally, the detailed operation of the apparatus shown will now be given. For this purpose it will be assumed that the subscriber at the automatic substation A, Fig. 1, desires to converse with the subscriber at the automatic substation A', Fig. 4.

50 When the subscriber at substation A removes his receiver, line relay 6 of the line switch C energizes over line conductors 2 and 3 and places ground on private normal conductor 4 at armature 12, thereby making 55 the called line busy in the banks of the connectors having access to it and closing a circuit for switching relay 5 and stepping magnet 7 in series. Line relay 6 also connects test wiper 16 to the junction of the 60 windings of switching relay 5 and stepping magnet 7 at armature 13. In case the trunk upon which the wipers 14-17, inclusive, of the line switch are standing is idle, this latter operation is of no utility and switching relay 5 energizes immediately, seizing

the trunk. Assuming, however, that the trunk upon which the wipers of the line switch are standing is busy, switching relay 5 is short circuited by the ground potential encountered on the busy test contact by test 70 wiper 16 and does not energize. This same ground potential encountered by test wiper 16 causes the energization of stepping magnet 7, and the wipers of the line switch are advanced step by step in search of an idle 75 trunk owing to the buzzer-like action of stepping magnet 7, which interrupts its own circuit.

When an idle trunk is reached, which trunk, it will be assumed, is the one comprising conductors 18-21, inclusive, switching relay 5 is no longer short circuited and energizes in series with stepping magnet 7. Stepping magnet 7, however, does not energize at this time on account of the high resistance of switching relay 5. Upon energizing, switching relay 5 opens a point in the test circuit and prepares the holding circuit at armature 10; connects the magnet of the meter M through wiper 15 to the 90 meter operating conductor 19 at armature 9; and at armatures 8 and 11 disconnects line conductors 2 and 3 from the winding of line relay 6 and ground, respectively, and extends them by way of wipers 14 and 17 95 and conductors 18 and 21, to the windings of line relay 31 of the selector repeater D. Line relay 31, upon energizing, closes a circuit for release relay 32 at armature 52. Release relay 32, upon energizing, opens a 100 point in the circuit of release magnet 40 and prepares a circuit for vertical magnet 43 at armature 54, and at armature 53 it places ground on release trunk conductor 20, thereby completing the usual holding 105 circuit for switching relay 5 of the line switch C before the slow acting line relay 6 has had time to deenergize.

As a further result of the energization of line relay 31, it completes at armature 51 110 a circuit for relay 37 as follows: from ground by way of the normally closed contacts controlled by armature 77 of relay 39, the upper winding of relay 37, resting contact and armature 64, working contact and armature 51, normally closed contacts controlled by armature 72, and resistance 46 to battery. Relay 37 thereupon energizes over this circuit and completes at armature 68 a circuit for relay 38 which includes armature 67 of 115 relay 36 and its resting contact. Responsive to the closure of this circuit, relay 38 energizes and opens at armature 70 a point in the circuit of switch-over relay 35, so as to prevent the energization of switch-over 120 relay 35 until the proper time occurs.

As a further result of the energization of the release relay 32, it places the dial tone on the lower heavy talking conductor at armature 55. This dial tone is transmitted to the 125

calling subscriber to inform him that he may now proceed to set up the connection. Accordingly, he manipulates his calling device in accordance with the first digit 1 in the desired number. When this occurs, line relay 31 deenergizes once momentarily and closes a circuit for vertical magnet 43 as follows: from ground by way of armature 52 and its resting contact, armature 54 and its working contact, armature 75 and its resting contact, and vertical magnet 43 to battery. By the operation of vertical magnet 43, the wipers 79-81, inclusive, are raised opposite the first level of bank contacts. The slow 10 acting relay 33 is energized in multiple with vertical magnet 43 and at armature 56 closes a point in the circuit of stepping relay 34, which is completed at off normal contacts 45 as follows: from ground by way of the working contact and armature 53, armature 62 and its resting contact, working contact and armature 56, armature 76 and its resting contact, off normal contacts 45, and stepping relay 34 to battery. Stepping relay 34, upon 15 energizing, prepares a circuit for rotary magnet 41 at armature 58, and at armature 57 closes a locking circuit for itself as follows: from ground by way of the grounded release trunk conductor 20, normally closed 20 contacts controlled by armature 63, armature 74 and its resting contact, armature 57 and its working contact, interrupter contacts 42 of rotary magnet 41, and thence to battery through off normal contacts 45 and stepping 25 relay 34.

When the slow acting relay 33 deenergizes at the end of the vertical movement, it opens the initial circuit of stepping relay 34 and completes a circuit for rotary magnet 41 as follows: from ground by way of the grounded release trunk conductor 20, armature 62 and its resting contact, normally closed contacts controlled by armature 56, armature 58 and its working contact, and rotary magnet 41 to battery. Responsive to the closure of this circuit, rotary magnet 41 energizes and advances the wipers 79-81, inclusive, into engagement with the first set of bank contacts in the selected level and, near the end of its stroke, opens at interrupter contacts 42 the locking circuit of stepping relay 34. When this occurs, stepping relay 34 deenergizes and opens the circuit of rotary magnet 41 at armature 58, resulting in the deenergization of rotary magnet 41. In case the trunk line connected with the first set of bank contacts is idle, switching relay 39 energizes immediately and seizes the trunk. Assuming the trunk to be busy, 40 however, switching relay 39 is short circuited by the ground potential encountered upon the busy test contact by test wiper 80 and does not energize, and stepping relay 34 is again energized through interrupter contacts 42 and off normal contacts 45 and

again closes its locking circuit at armature 57, and the circuit of rotary magnet 41 at armature 58, whereupon rotary magnet 41 again energizes and advances the wipers into engagement with the next set of bank 70 contacts.

This alternate operation of stepping relay 34 and rotary magnet 41 continues until an idle trunk is reached, which trunk, it will be assumed, is the one comprising conductors 75 85 and 86 and extending to the incoming selector repeater E, Fig. 2. When this idle trunk is reached, switching relay 39, being no longer short circuited, energizes from 80 ground on the grounded release trunk conductor 20 and in series with stepping relay 34 (stepping relay 34 not energizing at this time on account of the high resistance of switching relay 39) and opens the test circuit and places ground on the test wiper 80 85 at armature 73; removes stepping relay 34 from under the control of relay 33 at armature 76; disconnects vertical magnet 42 from in multiple with the slow acting relay 33 at armature 75; disconnects ground from armature 57 of stepping relay 34 and prepares a 90 circuit for relay 35 at armature 74; disconnects the dial tone machine from the lower talking conductor at armature 78; and at armatures 72 and 77 connects the wipers 79 and 81 to the bridge including the upper winding of relay 37, and disconnects the said bridge from battery and ground locally. Relay 37 is now maintained energized in series with line relay 101 of the incoming selector repeater E, Fig. 2, which is connected to conductor 85 through the normally closed contacts controlled by armature 143, and through the upper left hand repeating coil winding, conductor 86 being 105 grounded through the lower left hand repeating coil winding, the normally closed contacts controlled by armature 134, and the normally closed contacts controlled by armature 142. Since relay 37 is maintained energized in series with the line relay of the switch E, it maintains the circuit of relay 38 closed at armature 68, which relay in turn maintains the circuit of the switch-over relay 35 open at armature 70, which is the 110 last remaining open point in the circuit of the said relay 35.

In the incoming selector repeater E, Fig. 2, line relay 101 energizes responsive to the above mentioned closure of its circuit and closes at armature 125 a circuit for release relay 102. Release relay 102, upon energizing, places ground on locking conductor 118 at armature 127, and at armature 128 prepares a circuit for vertical magnet 117. 120 As a further result of the energization of line relay 101, it completes a circuit for the lower winding of relay 105 at armature 126. This circuit includes the normally closed contacts controlled by armature 152 of switching re- 125 130

lay 111, and the resting contact and armature 141, as well as the normally closed contacts controlled by armature 147, and the resistance 119. Relay 105, upon energizing, 5 closes a circuit at armature 133 for relay 108. This circuit includes armature 144 and its resting contact. Relay 108, upon energizing, opens at armature 139 a point in the circuit of switch-over relay 110, so as to 10 prevent the premature operation of the said relay.

When the calling subscriber manipulates his calling device in accordance with the second digit in the desired number, the interruptions produced by his calling device are repeated at armature 51 by line relay 31, which also closes a circuit for relay 33 at armature 52. Relay 33 accordingly energizes and, being slow acting, maintains its 20 armature attracted throughout the series of interruptions. Upon energizing, relay 33 closes a multiple circuit for relay 38 at the normally open contacts controlled by armature 56 in order to maintain relay 38 energized independent of armature 68 of relay 37, whose circuit, as above pointed out, is opened at armature 51. It will be understood that relay 33 is able to attract its armature 56 and closes the circuit of relay 38 before relay 37 can retract its armature 68 and open the circuit of relay 38, owing to the fact that a relay that is not stiffly adjusted is able to energize and attract its armature in a shorter time than is required 30 for a similarly adjusted relay to deenergize and retract its armature. Accordingly, relay 38 remains energized during the series of interruptions and, at the end of the last interruption, its circuit is again closed at armature 68 of relay 37 before its circuit is opened at the normally open contacts controlled by armature 56 of relay 33. This operation, it will be understood, is repeated for each of the remaining digits.

In the incoming switch E, line relay 101 deenergizes in response to each of the above 45 interruptions and closes at armature 125 a circuit for vertical magnet 117 through armature 128 and its working contact and armature 151 and its resting contact. By the operation of vertical magnet 117, the wipers 153-155, inclusive, are raised step by step in the usual manner and comes to rest opposite the desired level of bank contacts. Slow acting relay 103 is energized 50 in multiple with vertical magnet 117 and closes at armature 129 a circuit for stepping relay 104, which circuit includes armature 149 and its resting contact and the off normal contacts 113 which are closed upon the first vertical step. Stepping relay 104, upon energizing, prepares a circuit for vertical magnet 115 at armature 130, and at armature 131 closes a locking circuit for itself 60 as follows: from ground by way of the

grounded locking conductor 118, normally closed contacts controlled by armature 145 of relay 110, armature 150 and its resting contact, working contact and armature 131, interrupter contacts 116, and thence to battery by way of off normal contacts 113 and stepping relay 104.

When slow acting relay 103 deenergizes at the end of the vertical movement, it opens the initial circuit of stepping relay 104 at 75 armature 129, and at the normally closed contacts controlled by the said armature 129 completes a circuit for rotary magnet 115. Rotary magnet 115 now energizes and rotates the wipers 153-155, inclusive, 80 into engagement with the first set of bank contacts in the selected level, after which the operations are as described hereinbefore in connection with the first selector repeater D, until an idle trunk is selected, 85 which trunk, it will be assumed, is the trunk comprising conductors 161-163, inclusive, and extending to the thousands selector F, Fig. 3. When this idle trunk is reached, switching relay 111 energizes in series with 90 the stepping relay 104 (stepping relay 104 not energizing on account of the high resistance of switching relay 111) and opens the test circuit and grounds the test wiper 154 at armature 148; disconnects vertical magnet 95 117 at armature 151; removes stepping relay 104 from under the control of slow acting relay 103 at armature 149; disconnects the grounded locking conductor 118 from armature 131 of relay 104 and closes a circuit for 100 relay 109 through armature 139 at armature 150, leaving the circuit of the change-over relay 110 open only at armature 139 of relay 108. Relay 109 now energizes preparatory to giving momentary assistance during the 105 switch-over operation which is to take place subsequently. At armatures 147 and 152 relay 111 connects the wipers 153 and 155 to the bridge which includes the lower winding of relay 105, and at the same time disconnects the local battery and ground connections from the said bridge. Relay 105 is now maintained energized in series with line 110 relay 201 of the selector F, Fig. 3, which line relay 201 accordingly energizes and closes 115 at armature 221 a circuit through the resistance 212 and the lower contact and off normal spring 211 for the combined release and change-over relay 202. Relay 202, upon energizing, closes a point in the circuit of stepping relay 203 at armature 222, which circuit is still maintained open at off normal contacts 210; opens at armature 223 a point in the circuit of release magnet 205 and prepares a circuit for vertical magnet 207; and 120 at armature 213 connects the grounded release trunk conductor 162 to armature 221, and disconnects direct ground therefrom at the normally closed contacts controlled by 125 armature 213. This is done so as to enable 130

the selector F to be released in a manner to be pointed out hereinafter in case the calling subscriber hangs up without dialling another digit.

When the calling subscriber manipulates his calling device in accordance with the third digit in the desired number, the interruptions produced by his calling device are repeated in the manner described hereinbefore at armature 51 by line relay 31 of the first selector repeater D and the repeated interruptions are repeated in the same manner at armature 126 by line relay 101 of the incoming selector repeater E, Fig. 2. Line relay 101 also closes at armature 125 a circuit for the slow acting relay 103, which is accordingly maintained energized throughout the series of interruptions and maintains the circuit of relay 108 closed at the normally open contacts controlled by armature 129 independent of armature 133 of relay 103, which relay deenergizes responsive to the interruptions in the control circuit at armature 126.

In the selector F, Fig. 3, line relay 201 is deenergized once momentarily each time its circuit is interrupted by the line relay of the switch E and, upon each deenergization, closes a circuit for vertical magnet 207 as follows: from ground by way of the grounded release trunk conductor 162, (which is maintained grounded through wiper 154 of the switch E) armature 213 and its working contact, resting contact and armature 228, armature 221 and its resting contact, armature 223 and its working contact, and vertical magnet 207 to battery. By the operation of vertical magnet 207, the wipers 230-232, inclusive, are raised step by step and come to rest opposite the desired level of bank contacts. Upon the first vertical step of the switch, off normal contacts 210 complete a circuit for stepping relay 203 as follows: from ground by way of the grounded release trunk conductor 162, which conductor is maintained grounded by the incoming selector repeater E, Fig. 2, working contact and armature 222, off normal contacts 210, and stepping relay 203 to battery. Stepping relay 203 thereupon energizes and prepares a circuit for rotary magnet 208 at armature 224, and at armature 225 closes a locking circuit for itself. This locking circuit includes the resting contact and armature 228, as well as the interrupter contacts 209, in addition to the off normal contacts 210. As a further result of the first vertical step, off normal spring 211 disconnects relay 202 from the working contact of armature 221 of the line relay 201 and connects it in multiple with vertical magnet 207. Accordingly, an impulse of current is transmitted to relay 202 in multiple with vertical magnet 207 upon each deenergization of line relay 201, and the slow acting relay 202 is maintained energized until the end of the vertical

movement, at which time it falls back responsive to the prolonged opening of its circuit by the line relay. Upon deenergizing, relay 202 disconnects the resting contact of the now operated armature 221 from the vertical magnet 207 and from its own winding, and prepares a circuit for the release magnet 205 at armature 223; replaces ground locally on armature 221 of line relay 201 and disconnects release trunk conductor 162 therefrom at armature 213; and opens at armature 222 the initial circuit of stepping relay 203 and completes the circuit of rotary magnet 208 through armature 224 and its working contact. Rotary magnet 208 thereupon energizes and advances the wipers 230-232, inclusive, into engagement with the first set of bank contacts in the selected level and, near the end of its stroke, opens the locking circuit of stepping relay 203 at interrupter contacts 209, whereupon stepping relay 203 deenergizes and opens the circuit of rotary magnet 208 at armature 224, resulting in the deenergization of rotary magnet 208, which again closes its interrupter contacts 209.

In case the trunk terminating in the first set of contacts is idle, switching relay 204 energizes immediately in series with stepping relay 203 and seizes the trunk. Assuming the trunk to be busy, however, switching relay 204 is short circuited by the ground potential encountered upon the busy test contact by test wiper 231, and stepping relay 203 is energized again, with the result that the circuit of rotary magnet 208 is again closed at armature 224 and the wipers are advanced into engagement with the next set of bank contacts. This alternate operation of stepping relay 203 and rotary magnet 208 continues, as described, until an idle trunk is reached, which trunk, it will be assumed, is the one comprising conductors 233-235, inclusive, and extending to the hundreds selector G.

When this idle trunk is reached, switching relay 204, being no longer short circuited, energizes in series with stepping relay 203, the said stepping relay 203 not energizing on account of the high resistance of switching relay 204; disconnects ground from armature 221 of line relay 201 at armature 228, so as to prevent the energization of release magnet 205 upon the deenergization of line relay 201, which occurs subsequently; disconnects test wiper 231 from the junction of its own winding and that of stepping relay 203 and connects it to the grounded release trunk conductor 162 at armature 227, thereby grounding release trunk conductor 234 of the seized switch; and at armatures 226 and 229, connects the wipers 230 and 232 to the incoming trunk conductors 161 and 163 and disconnects line relay 201 from the latter, whereupon line relay 201 deenergizes and

closes a point in the circuit of release magnet 205 at armature 221.

In the seized selector G, line relay 251 and relay 252 now energizes and perform the function which is described for the relays 201 and 202 of the selector F.

When the calling subscriber manipulates his calling device in accordance with the next digit in the desired number, the selector G responds in the same manner as described in connection with the selector F, and raises its wipers 236-238, inclusive, to the desired level, after which it selects an idle trunk in the same manner as described for the selector F, which trunk, it will be assumed, is the one comprising conductors 241-243, inclusive, and extending to the connector H. When this idle trunk is reached, switching relay 253 of the selector G energizes and seizes the said trunk, whereupon ground is extended to the release trunk conductor 242 and the incoming trunk conductors 233 and 235 are extended to the trunk conductors 241 and 243 of the connector H, and line relay 251 is cut off.

In the connector H, line relay 301, which is bridged across conductors 241 and 243 at off normal contacts 307 and 308, now energizes and closes a circuit for release relay 302 as follows: from ground by way of the normally closed contacts controlled by armature 323 of release relay 302, armature 339 and its resting contact, armature 331 and its resting contact, armature 321 and its working contact, and release relay 302 to battery. Release relay 302, upon energizing, closes a locking circuit for itself at armature 324 which is independent of armature 321 and its working contact; shifts its initial circuit at armature 323 from ground locally to ground by way of the grounded release trunk conductor 243; opens a point in the circuit of release magnet 310 at armature 325 and prepares the operating circuit; and at armatures 322 and 326 shunts the off normal contacts 307 and 308, respectively, so as to maintain the line relay 201 bridged across the trunk conductors 241 and 243 after these off normal contacts have been opened upon the first vertical step of the switch, which occurs subsequently.

As a further result of the above mentioned energization of line relay 301, relay 303 is energized in multiple with release relay 302 through off normal contacts 309. Upon energizing, relay 303 disconnects the operating conductor at armature 328 from the rotary magnet 321 and connects it to the vertical magnet 313.

When the calling subscriber manipulates his calling device in accordance with the next digit in the desired number line relay 301 is deenergized a corresponding number of times and, upon each deenergization, completes a circuit for vertical magnet 313,

which extends from ground as previously traced to armature 321, and thence by way of the resting contact of the said armature, armature 325 and its working contact, armature 328 and its working contact, and vertical magnet 313 to battery. By the operation of vertical magnet 313, the wipers 341-343, inclusive, are raised step by step and come to rest opposite the desired level of bank contacts. Upon the first vertical step, off normal contacts 307 and 308 open, leaving line relay 301 bridged across the line only through armature 322 and its working contact and armature 323 and its working contact of relay 302. Slow acting relay 305 is energized in multiple with vertical magnet 313 and at armature 334 extends ground from the grounded release trunk conductor 242 through armature 350 and its working contact, to relay 303 before the initial circuit of relay 303 is opened at off normal contacts 309 upon the first vertical step.

At the end of the vertical movement slow acting relay 305 deenergizes and opens the circuit of relay 303 at armature 334, whereupon relay 303 deenergizes and opens its locking circuit at armature 350, and at armature 328 disconnects vertical magnet 313 and connects up rotary magnet 312.

When the calling subscriber manipulates his calling device in accordance with the next and final digit in the desired number, line relay 301 is deenergized a corresponding number of times and, upon each deenergization, completes the circuit of rotary magnet 312, whereupon the wipers 341-343, inclusive, are rotated into engagement with the bank contacts in which the line of substation A' terminates. Slow acting relay 305 is again maintained energized during the series of deenergizations of line relay 301 and at armature 333 disconnects test wiper 342 from the upper winding of switching relay 306 and connects it instead to busy relay 304. Relay 305 also places a shunt around armature 331 and its resting contact at armature 335, so as to prevent the premature opening of the circuit of release relay 302 in case busy relay 304 energizes due to test wiper 342 passing over busy test contacts during the rotary movement.

Assuming the called line to be busy, busy relay 304 is energized when test wiper 342 arrives at the test contact of the called line, and prepares a locking circuit for itself at armature 330 and at armature 331, opens a point in the circuit of release relay 302, while at armature 332 it prepares the busy signalling circuit. Accordingly, when relay 305 falls back at the end of the rotary movement, busy relay 304 becomes locked to the grounded release trunk conductor 243 through the normally closed contacts controlled by armature 337, its own armature 125

330 and its working contact, and the normally closed contacts controlled by armature 333, resulting in the calling subscriber being given a busy signal in a manner to be described hereinafter.

When the calling subscriber hears the busy tone, he replaces his receiver whereupon the switches involved in the attempted connection are released in a manner to be explained more in detail hereinafter.

It will now be assumed that, when the subscriber at substation A' is called by the subscriber at substation A in the hereinbefore described manner, the line of substation A' is idle. That being the case, no circuit is closed for busy relay 304 when the wipers 341-343, inclusive, arrive upon the bank contacts of the called line and, when relay 305 deenergizes it disconnects busy relay 304 at armature 333 and completes a circuit for the upper winding of switching relay 306 as follows: from ground by way of the grounded release trunk conductor 242, normally closed contacts controlled by armature 337, armature 330 and its working contact, upper winding of switching relay 306, resting contact and armature 333, wiper 342, private normal conductor 345, switching relay 347 of the called line switch C', and stepping magnet 349 to battery. Switching relay 347 energizes over this circuit, but stepping magnet 349 does not energize on account of the high resistance of switching relay 347. Relay 347, however, pulls up only half way on account of the usual interlocking device (not shown) between its armature proper and that of line relay 348. Accordingly, the bridge across the line conductors is removed but the associated wipers are not connected up.

In the connector H, switching relay 306 energizes in series with relay 347 over the above traced circuit, but due to the fact that it has a copper slug on its armature end, as is denoted by the black upper portion of the core, it is slightly slow in pulling up so as to give plenty of time for the energization of relay 347 to become effective before the line wipers are connected up. Upon pulling up, relay 306 closes a locking circuit for itself at its lightly adjusted armature 338; connects the grounded release trunk conductor 242 to test wiper 342 at armature 337, at the same time disconnecting armature 330 of busy relay 304 from the said release trunk conductor 242 so as to prevent the upper winding of switching relay 306 from being short circuited and having a retarding effect upon the release of the relay when the circuit of the lower winding is subsequently opened; and at armatures 336 and 340 connects up the line wipers 341 and 343, respectively, whereupon ringing current is intermittently projected out over the called line to ring the bridged bell at the substation A'.

As a further result of the energization of switching relay 306, it brings about the switch-over operation in a manner to be pointed out, resulting in the circuits in the switches D and E being shifted from dialing position into position to await the answering of the called subscriber. Specifically relay 306 opens the circuit of release relay 302 and prepares a locking circuit for ring cut-off relay 303 at armature 339. Relay 302 thereupon deenergizes; disconnects line relay 301 at armatures 332 and 326, allowing it to fall back; prepares the release magnet circuit at armature 325; opens a point in its previously established locking circuit at armature 324; and at armature 323 disconnects the grounded release trunk conductor 342 from armature 339 and replaces local ground on the said armature so as to provide a circuit for subsequently energizing release magnet 310.

In the incoming selector repeater E, Fig. 2, relay 105 deenergizes responsive to line relay 301 being disconnected in the connector H, as pointed out above, and opens the circuit of relay 108 at armature 133, whereupon relay 108 deenergizes and opens at armature 139 the circuit of relay 109 and completes a circuit for switch-over relay 110. Relay 109, however, being slow acting, does not deenergize immediately. The circuit of relay 110 which is closed at armature 139 is as follows: from ground by way of the grounded locking conductor 118, normally closed contacts controlled by armature 145, armature 150 and its working contact, armature 139 and its resting contact, and switch-over relay 110 to battery. Relay 110 thereupon energizes and closes a locking circuit for itself at armature 145; opens a further point in the circuit of slow acting relay 109 at well as its own initial circuit at the normally closed contacts controlled by armature 145; prepares a holding circuit for line relay 101 at the normally open contacts controlled by armature 145; removes relay 108 from under the control of relay 105 at armature 144; completes a local circuit for line relay 101 through armature 140 and its working contact at armature 142, at the same time removing ground from the lower left hand repeating coil winding and consequently from the lower trunk conductor 86; and at armature 143 bridges the high resistance relay 107 across the condenser inserted between the left hand windings of the repeating coil; and disconnects line relay 101 from the upper left hand repeating coil winding at the normally closed contacts controlled by the said armature 143, thereby completely substituting the high resistance bridge including relay 107 for the battery and ground connections across conductors 85 and 86.

At armature 141 relay 110 disconnects the bridge including the lower winding of relay 110

105 from across the wipers 153 and 155, and at armatures 141 and 146 connects the wipers 153 and 155 to battery and ground, respectively, through the upper and lower repeating coil windings, wiper 151 being connected to battery through the upper right hand repeating coil winding, armature 141 of the now energized relay 109 and its working contact, and the upper windings of relays 105 and 106 in series, and wiper 155 being connected to ground through the lower right hand repeating coil winding and the lower winding of the differential relay 106. This bridge is closed across the line wipers preparatory to feeding talking battery to the called substation when the subscriber thereat responds and, since it is desired to subsequently place the continuity of this bridge under the control of supervisory relay 107 after the switch-over operation in the first selector repeater has been completed, the bridge is closed as above pointed out through armature 141 and its working contact of the slow acting relay 109, which will fall back subsequently and leave relay 107 to control the bridge at armature 136 as will herein-after appear.

In the first selector repeater D, Fig. 1, relay 37 deenergizes in response to the removal of the current source from the bridge across conductors 85 and 86 in the incoming selector E, Fig. 2, as described above and opens the circuit of relay 38 at armature 68, whereupon relay 38 deenergizes and closes a circuit for relay 35 as follows: from ground by way of the grounded release trunk conductor 20, normally closed contacts controlled by armature 63, armature 74 and its working contact, armature 70 and its resting contact, and relay 35 to battery. Relay 35 thereupon energizes; closes a locking circuit for itself and opens the initial circuit at armature 63, at the same time preparing a locking circuit for relay 38; disconnects ground from the working contact of armature 56 of relay 33 at armature 62, so as to render any subsequent energization of relay 33 ineffective in operating relay 38; at armature 62 and its working contact prepares a circuit for grounding the meter operating conductor 19 upon the next energization of relay 38; completes the inductive connection between the calling line and the switch wipers through the talking condensers at armatures 61 and 66; at armature 64 disconnects the upper winding of relay 37 from across the line wipers 79 and 81; and at armatures 64 and 65 bridges the differential relay 36 and the battery feed relay 37 in series across the line wipers 79 and 81, ground being extended to wiper 81 through the lower winding of the differential relay 36, working contact and armature 65, upper winding of relay 37, and the working contact and armature 77, and battery being ex-

tended to wiper 79 through the lower winding of the battery feed relay 37, upper winding of the differential relay 36, working contact and armature 64, working contact and armature 51, and the working contact and armature 72.

In the incoming selector repeater E, Fig. 2, the high resistance relay 107, which is bridged around the left hand condenser associated with the repeating coil winding as pointed out hereinbefore, is now energized over the line conductors responsive to the above mentioned circuit changes, which resulted in battery and ground being supplied to wipers 79 and 81 of the first selector repeater D, Fig. 1, through relays 36 and 37. Relay 36 of the switch D is not energized because its windings are differentially connected at this time and relay 37 does not energize on account of the high resistance of relay 107 in the incoming selector repeater E.

Relay 107, upon energizing, closes the following circuit for relay 101 before relay 109, which is now holding relay 101 energized at armature 140, has had time to deenergize from ground by way of the grounded locking conductor 118, normally open contacts controlled by armature 145 of switch-over relay 110, armature 137 of relay 107 and its working contact, and relay 101 to battery. As a further result of the energization of relay 107, it shunts armature 141 of relay 109 at armature 136 so as to hold the battery feed bridge closed after relay 109 has fallen back.

The circuits are now in readiness for the answering supervision to be relayed back to operate the meter M when the called man answers.

When the subscriber at substation A' responds to the ringing of his bell by removing his receiver, the direct current bridge including his receiver and transmitter is substituted for the ringer bridge including the condenser, whereupon ring cut-off relay 303 of the connector H responds; closes a locking circuit for itself at armature 350, which circuit includes the normally closed contacts controlled by armature 323 of relay 302 and armature 339 and its working contact; and at armatures 327 and 329 disconnects the line wipers 341 and 343 from its own winding and ground and connects them instead to the conductors 241 and 243, thereby finally completing the talking circuit. Talking battery is now supplied to the called substation A' through the upper and lower windings of the differential relay 106 in the incoming selector repeater E, Fig. 2, the upper winding of supervisory relay 105 and the right hand repeating coil windings. Accordingly, supervisory relay 105 becomes energized and attracts its armatures 132 and 133. Relay 106, however, is not energized

at this time owing to the fact that it is differentially wound. Upon energizing, supervisory relay 105 shunts the high resistance upper winding of the front bridge relay 5 107 at armature 132, whereupon the resistance of the front bridge is lowered sufficiently to permit the back bridge relay 37 in the first selector repeater D to energize. Relay 36, however, which is connected in 10 series with relay 37, is not energized at this time owing to the fact that it is differentially wound. Accordingly, relay 37, upon energizing, completes at armature 68 a circuit for relay 38 which includes armature 67 and 15 its resting contact. Relay 38, upon energizing at this time, closes a locking circuit for itself at armature 71 as follows: from ground by way of the grounded release trunk conductor 20, normally open contacts 20 controlled by armature 63 of switch-over relay 35, armature 71 and its working contact, and relay 38 to battery. Relay 38 also closes at armature 69 a circuit for the meter M as follows: from ground by way of the 25 grounded release trunk conductor 20, armature 62 and its working contact, working contact and armature 69, the meter operating conductor 19, contact in the bank of wiper 15 and said wiper, working contact and 30 armature 9, and the magnet of the meter M to battery. Upon energizing, the magnet of the meter M advances the associated number wheels to register the successful call. Since relay 38 is now locked energized 35 at armature 71 independent of relay 37, as above pointed out, the magnet of the meter M remains energized until the connection is released regardless of any operations of the called subscriber's switch-hook.

40 When the conversation is terminated, the subscribers at substations A and A' replace their receivers. Assuming that the receiver at substation A' is replaced first, supervisory relay 105 in the incoming selector repeater E deenergizes responsive to the called subscriber's receiver being replaced and at armature 132 removes the shunt from around the upper winding of the high resistance relay 107, whereupon relay 37 in the 45 first selector repeater D deenergizes and opens the initial circuit of relay 38 at armature 68. Relay 38, however, does not deenergize owing to its previously traced locking circuit.

50 When the receiver is replaced at substation A, line relay 31 of the first selector repeater D deenergizes and opens at armature 52 the circuit of release relay 32 and at armature 51 opens the bridge across wipers 55 79 and 81. Release relay 32, being slow acting, does not fall back for an interval. Relay 107, however, of the incoming selector repeater E, Fig. 2, immediately deenergizes responsive to the release of armature 51 of line relay 31 of the switch D; opens at armature 136 the battery feed bridge across the wipers 153 and 155 and opens at armature 137 the circuit of line relay 101, whereupon line relay 101 deenergizes also and opens at armature 125 the circuit of release 70 relay 102 and closes a circuit for relay 103 through armature 128 and its working contact. Relay 103 now energizes and closes a circuit for relay 108 at the normally open contacts controlled by armature 129, whereupon relay 108 energizes and attempts to close a circuit for relay 109 at armature 139. This circuit, however, is now open at contacts controlled by armature 145.

75 In the first selector repeater D, Fig. 1, release relay 32 deenergizes after the interval for which it is adjusted and removes ground from release trunk conductor 20 at armature 32, at the same time opening the circuit of the slow acting relay 33 (which energized responsive to the deenergization of line relay 31) and closing a circuit for release magnet 40 at armature 54. Responsive to the removal of ground from release trunk conductor 20, switch-over relay 35, switching relay 39, and the meter operating relay 38 deenergize. The deenergization of relays 35 and 39 does not have any particular function at this time except to restore the circuits controlled thereby to normal, and the deenergization of relay 38 results merely in the opening of the circuit of the magnet of the meter M, whereupon the said magnet deenergizes. Responsive to the closure of its circuit at armature 54, release magnet 40 energizes through off normal contacts 44, whereupon the wipers 79-81, inclusive, of the selector D are restored to normal position in the usual manner and the circuit of release magnet 40 is thereupon opened at off 90 normal contacts 44.

100 As a further result of the removal of ground potential from release trunk conductor 20, the busy potential is removed from private normal conductor 4 of the calling line and switching relay 5 of the line switch C deenergizes.

105 In the incoming selector repeater E, Fig. 2, upon the deenergization of release relay 102 at the end of the interval for which it is 110 adjusted, ground is removed from conductor 118 at armature 127, whereupon relays 108, 110, and 111 deenergize. As a further result of the deenergization of release relay 102, it opens the circuit of slow acting relay 103 and completes a circuit for release magnet 112 at armature 128, resulting in the subsequent deenergization of relay 103. Responsive to the energization of release magnet 112, the wipers of the switch are restored to normal position in the usual manner, whereupon the circuit of release magnet 112 is opened at off normal contacts 114.

115 120 As a further result of the above mentioned deenergization of release relay 102 of the in- 130

coming selector repeater E, ground is removed from the private wiper 154 which results in the holding ground for the switches F, G, and H being removed. When this occurs, switching relay 204 in the selector F, switching relay 253 in the selector G, and switching relay 306 in the connector H deenergize. The deenergization of switching relay 204 of the selector F results in a circuit being closed for release magnet 205 as follows: from ground by way of the normally closed contacts controlled by armature 213, resting contact and armature 228, armature 221 and its resting contact, armature 223 and 10 its resting contact, off normal contacts 206, and release magnet 205 to battery. Upon the energization of release magnet 205, the wipers of the selector F are restored to normal position in the usual manner. The 15 selector G is restored to normal position in the same manner as the selector F.

In the connector H, release relay 306, upon deenergizing, opens the locking circuit of relay 303 at armature 339, resulting in the de- 20 energization of relay 303, and at armature 339 and its resting contact closes a circuit for release magnet 310 as follows: from ground by way of the normally closed contacts controlled by armature 323 of relay 302, armature 339 and its resting contact, armature 331 and its resting contact, armature 321 and its resting contact, armature 325 and its resting contact, off normal contacts 311, and release magnet 310 to battery. Release magnet 310 now energizes and the wipers of the switch are restored to normal position in the usual manner.

The entire connection is now released and the switches involved are in readiness to be used in a subsequent connection. It will now be assumed that the subscriber at substation A desires to converse with the subscriber at substation A', Fig. 9, whose line terminates in an office which has not yet been converted to automatic operation. That being the case, the connection must be completed by a "B" operator in the manual office, whose position is indicated in Fig. 9. Accordingly, the subscriber at substation A removes his receiver and dials the necessary digits to trunk the call to the desired manual office. In this case it has been assumed that the desired manual office is in the same district as the automatic office in which the line 45 of substation A', Fig. 4, terminates. Accordingly, the incoming selector repeater E, Fig. 2, whose function from a trunking standpoint is that of an office selector, may be used to complete the connection to the operator's position after it has been seized by a district selector, such as the first selector repeater D, Fig. 1.

When the receiver is removed at substation A, the line switch C operates in the 50 hereinbefore described manner to select an

idle trunk, which trunk, it will be assumed, is the one extending to the first selector repeater D. Accordingly, the line and release relays 31 and 32 of the first selector repeater D energize following the energization of the switching relay 5 of the line switch C and perform the functions pointed out hereinbefore.

When the calling subscriber operates his calling device in accordance with the first 75 digit, the switch D raises its wipers in the hereinbefore described manner and selects an idle trunk, which will be assumed to be the trunk comprising conductors 85 and 86 and extending to the incoming selector repeater E, Fig. 2. Accordingly, the line and release relays 101 and 102 of the incoming selector repeater E energizes with the hereinbefore pointed out results.

When the calling subscriber manipulates his calling device in accordance with the second and last digit necessary to extend the connection to the "B" position shown in Fig. 9, the selector E raises its wipers opposite the desired level of contacts and selects an idle trunk in the hereinbefore described manner, which trunk, it will be assumed, is the one comprising conductors 164 and 165 and extending to the plug ending cord circuit shown in Fig. 9. That being the case, the energization of switching relays 111 of the selector E results in the extension of the calling loop to conductors 164 and 165. In this case, no battery feed is found to maintain relay 105 energized after the battery through resistance 119 has been disconnected at the normally closed contacts controlled by armature 147, and relay 105 deenergizes, opening the circuit of relay 108 at armature 133. Relay 105 accordingly deenergizes and completes the circuit of the switch-over relay 110 at armature 139, whereupon switch-over relay 110 energizes and connects up the back bridge circuit at armatures 141 and 146, and at armatures 142 and 143 substitutes the front bridge supervisory relay 107 for the line relay 101, whereupon the switch-over operation in the first selector D takes place as hereinbefore described.

At the "B" operator's position, Fig. 9, relay 801 now energizes responsive to the above mentioned switch-over operation in the incoming selector repeater E, Fig. 2, and closes a circuit for the supervisory lamp 808 at armature 807, which circuit includes armatures 810 and 811. The lamp 808 thereupon becomes lighted to inform the "B" operator of the call.

When the operator responds by throwing her combined listening and ringing key K³ into listening position, thereby connecting up her listening taps, the said key closes a circuit for relay 802 which energizes and locks itself up through armature 806 and 125

its working contact at armature 809. Relay 802 also extinguishes the lamp 808 at armature 810.

The "B" operator now converses with the calling subscriber and, upon learning his desire, inserts the plug of her cord circuit into the jack J², resulting in the energization of sleeve relay 803 in series with the cut-off relay of the called line, which cuts off relay energizes and removes the normal calling bridge. Relay 803, upon energizing, prepares a disconnect circuit for the supervisory lamp 808.

The operator now projects ringing current out over the called line intermittently by means of her key K³ and when the called subscriber responds, the supervisory relay 804 energizes and shunts the high resistance winding of relay 801 at armature 805, whereupon relay 105 in the incoming selector repeater E responds and short circuits the high resistance winding of relay 107 at armature 132. When this occurs, relay 37 in the first selector repeater D energizes and closes a circuit for the meter operating relay 38 at armature 68, whereupon relay 38 energizes and completes the hereinbefore traced circuit for the magnet of the meter M at armature 69.

The calling and called subscribers may now converse with each other as desired and when the conversation is terminated they replace their receivers.

When the receiver is replaced at substation A³, supervisory relay 804 deenergizes and removes the shunt from around the high resistance winding of relay 801, whereupon relay 105 of the incoming selector repeater E, Fig. 2, deenergizes and removes the shunt from around the high resistance winding of relay 107, resulting in the de-energization of relay 37 of the first selector repeater D, Fig. 1.

When the receiver is replaced at substation A, the first selector repeater D and the incoming selector repeater E release in the hereinbefore described manner.

Responsive to the bridge across the conductors 164 and 165 being removed by the incoming selector repeater E, relay 801 in the "B" operator's cord circuit, Fig. 9, de-energizes and completes at armature 807 a disconnects circuit for the lamp 808 through the working contact of armature 811 and said armature of the sleeve relay 803. Upon observing the lighted condition of the lamp 808, the "B" operator pulls down the connection, whereupon sleeve relay 803 deenergizes and extinguishes the lamp 808, and the cut-off relay of the called line deenergizes also.

In order to be able to point out clearly certain features of the present invention pertaining to the holding of the connection by an operator, it will be assumed that the

subscriber at substation A desires to make a toll call and must therefore first get into communication with the toll recording operator, who will see that the desired toll connection is set up. The toll recording operator's position is indicated in Fig. 8 and may be reached by the subscriber at substation A through the medium of a first selector repeater, such as the switch D, Fig. 1, and an incoming selector repeater, such as the switch E, Fig. 2.

It will be assumed that when the subscriber removes his receiver, the line switch C selects the selector D; and that, when the calling subscriber manipulates his calling device for the first digit, the selector D selects the trunk extending to the selector E; and that, when the calling subscriber manipulates his calling device in accordance with the second digit, the selector E selects the trunk comprising conductors 166 and 167 and extending to the trunk circuit at the toll recording operator's position, Fig. 8. Accordingly, the switch-over operations in the first selector repeater D and the incoming selector E take place responsive to the seizure of the trunk leading to the toll recording operator's position on account of the fact that no source of current is bridged across conductors 166 and 167 to maintain relay 105 energized. As soon as the switch-over operation in the incoming selector repeater E has taken place, battery is placed on wiper 153 through the upper right hand repeating coil winding, and ground is placed on wiper 155 through the lower right hand repeating coil winding, resulting in the energization of the high resistance line relay 702 at the toll recording operator's position, Fig. 8. Relay 702, upon energizing, closes at armature 705 a circuit through spring 709 of the answering key K' for the answering lamp 711, which accordingly becomes lighted.

When the toll recording operator notes the lighted condition of the lamp 711, she operates her answering key K', thereby extinguishing the answering lamp 711 at the spring 709, and she also manipulates her listening key K², thereby connecting up her listening taps to the talking circuit. The operator now converses with the calling subscriber and makes the proper record of his wants, after which she restores her listening key K², leaving the answering key K' operated.

When the calling subscriber replaces his receiver, line relay 31 of the selector D deenergizes and opens the bridge across the line wipers at armature 51 at the same time opening the circuit of release relay 32 at armature 52. Release relay 32, however, being slow acting, does not fall back immediately. In the incoming selector repeater E, relay 107 reenergizes in response to the energization of the line relay of 130

the switch D and opens the circuit of line relay 101 at armature 137, whereupon line relay 101 deenergizes and opens the circuit of the slow acting release relay 102 at armature 125. Relay 102, being slow acting, remains operated for the time being. Relay 107, also opens the bridge across the line wipers at armature 138, whereupon line relay 702 at the toll recording operator's position, Fig. 8, deenergizes and closes a disconnect circuit for the lamp 711 at armature 705. Relay 702 also closes at armature 704 a circuit for the holding relay 701 through spring 708 of the key K' and its associated contact. Relay 701, upon energizing, grounds locally the lower terminal of line relay 702 and disconnects it from the lower trunk conductor 167 at armature 707, and at armature 710 connects battery through resistance 706 to conductor 167.

In the selector repeater E, the differential relay 106 now energizes responsive to battery being placed on the lower talking conductor at the toll operator's position and closes at armature 138 a circuit for line relay 101 which includes armature 142 and its working contact. Line relay 101, upon energizing, closes at armature 125 a circuit for release relay 102 before the said relay has had time to deenergize. Differential relay 106 also connects a ground potential obtained from the grounded locking conductor 118 through the normally open contacts controlled by armature 145 to the lower terminal of relay 107 and disconnects the said terminal from conductor 86 at armature 134, and at armature 135 connects battery to conductor 86 through the lower left hand repeating coil winding. In the selector D, relay 37 and differential relay 36 now energizes in series responsive to the battery being placed on the lower talking conductor, and relay 36 closes at armature 67 a circuit for release relay 32 before the latter has had time to deenergize. The energization of relay 37 is merely incidental at this time.

In the above manner the entire connection is held up by the battery placed on the lower talking conductor at the toll recording operator's position. It will be appreciated that the principal novelty of this arrangement resides in the fact that a loop talking circuit is provided throughout and that the talking circuit in any one case is normally grounded at one end only, and that the grounded holding battery is connected to the lower talking conductor to hold up the connection after the calling subscriber has replaced his receiver and is not connected to the talking circuit during conservation.

Assuming that the calling subscriber replaced his receiver merely to attract the operator's attention because he desires to converse further, and that he again removes the receiver after a short interval, or that the

subscriber, instead of actually replacing his receiver, merely moved the switch-hook down and then let it up again, the disconnect lamp 711 at the operator's position, Fig. 8, is again extinguished when the receiver hook again moves upward as will now be explained. When the receiver hook rises, line relay 31 of the switch D energizes and places battery on the upper line wiper 79 at armature 51 through the upper winding of differential relay 36 and the lower winding of relay 37. This results in the energization of relay 107 of the incoming selector repeater E, which is connected to the upper talking conductor 85 through the upper left hand repeating coil winding of the incoming selector repeater E, and through the working contact and armature 143, and is grounded through the working contact and armature 134, the normally open contacts controlled by armature 145, and the grounded release trunk conductor 118. Relay 107, upon energizing, places battery on the line wiper 153 of the switch E at armature 136 through the upper windings of relays 105 and 106. This results in the energization of line relay 702 at the operator's position, the lower terminal of the said line relay being grounded through armature 707 and its working contact. Upon energizing, line relay 702 extinguishes the lamp 711 at armature 705, and at armature 704 opens the circuit of relay 701. Relay 701 thereupon deenergizes and restores the loop conditions to the trunk circuit, at the same time removing battery and ground from the said trunk circuit. Relay 702 is now maintained energized over the loop extending back to the incoming selector repeater E, Fig. 2, and the differential relay 106 deenergizes and retracts its armature 138, leaving the energization of line relay 101 under the control of relay 107, and restoring the loop connections across the trunk conductors 85 and 86 at the normally closed contacts controlled by armature 134, and removing the ground and battery connections at armatures 134 and 135. Consequently, the differential relay 36 and relay 37 in the first selector repeater D deenergize right away, and relay 36 opens the multiple circuit of release relay 32 at armature 67, leaving relay 32 energized through armature 52 of line relay 31. The circuit conditions are now the same as they were before the calling subscriber depressed his receiver hook, and the above operations may be repeated as many times as desired, in case he moves his receiver hook up and down several times solely to attract the attention of the operator.

Assuming that the calling subscriber has finished his conversation and does not remove his receiver after having replaced it with the above described results, the operator, upon noting the lighted condition of the lamp 711, restores her answering key

- in the desired number, resulting in a corresponding number of interruptions being produced in the circuit of line relay 501 of the incoming selector repeater D', Fig. 6. Accordingly, the switch D' operates in the hereinbefore described manner to raise its wipers opposite the desired level and select an idle trunk, which trunk, it will be assumed, is the one comprising conductors 85 and 86 and extending to the incoming selector repeater E, Fig. 2. Accordingly, upon the energization of switching relay 511 of the switch D', a bridge is placed across conductors 86 and 87, resulting in the energization of the line and release relays 101 and 102 of the switch E, and resulting in relay 505 of the switch D' being maintained energized in series with line relay 101 of the switch E.
- At the "A" operator's position, relay 462, associated with the calling device CD, is energized as soon as the calling device is moved from its normal position, and at armature 464 closes a multiple locking circuit for relay 437 independent of armature 463 of relay 461, which relay deenergizes while the calling device is returning to normal. Relay 462 is maintained energized until the calling device has reached its normal position and, being slow acting, maintains its armature attracted for a short time thereafter, after which it deenergizes leaving the locking circuit of relay 423 and the circuit of the lamp 466 under the control of relay 461.
- The "A" operator now manipulates her calling device in accordance with the remaining digits in the desired number, resulting in the incoming selector repeater E, Fig. 2, a thousands selector, such as F, Fig. 3, a hundreds selector, such as G, and a connector, such as H, Fig. 4, being operated to extend a connection to the line of substation A'.
- Assuming that the line of substation A' is busy when called, busy relay 304 remains energized after the connection is extended to the called line and, upon the deenergization of relay 305, the circuit of release relay 302 is opened at armature 335, whereupon relay 302 deenergizes and disconnects the line relay 301 at armatures 322 and 326, at the same time connecting the busy signalling conductor 175 through the working contact of armature 332 and said armature and the resting contact of armature 326 and said armature to the lower talking conductor 243.
- Responsive to the line relay 301 of the connector H being disconnected, relay 105 of the switch E deenergizes and opens the circuit of relay 108 at armature 133, whereupon relay 108 deenergizes and opens the circuit of the slow acting relay 108 and completes the circuit of switch-over relay 110 at armature 139. Relay 110 accordingly deenergizes and substitutes the battery feed bridge including both windings of the differential relay 106 and the upper winding of relay 105 for the calling bridge across the wipers 153 and 135 including the lower winding of relay 105. The battery branch of this bridge is maintained closed in the hereinbefore pointed out manner by the slow acting relay 109 at armature 138 pending the energization of relay 107. Relay 110 also substitutes the bridge including the high resistance relay 107 for the bridge across conductors 85 and 86 including the exchange battery and ground and the line relay 101. Responsive to this latter operation, relay 505 of the incoming selector repeater D' deenergizes with the same results pointed out in connection with the deenergization of relay 105 of the switch D. Briefly, the deenergization of relay 505 results in the deenergization of relay 508, which is followed by the energization of the change-over relay 510. One of the results of the energization of change-over relay 510 is that the bridge across the line wipers including the lower winding of relay 505 and the lower armature of relay 501 is opened at the upper armature of relay 510 and the bridge including the upper and lower windings of the differential relay 506, the upper winding of relay 505, and the lower armature of the now energized relay 509, in addition to the right hand repeating coil windings, is connected up at the upper and lower armatures of relay 510. When this occurs, the bridged relay 107 in the incoming selector repeater E, Fig. 2, energizes over conductors 85 and 86 and takes over the functions of the slow acting relay 109 at armatures 136 and 137 before the slow acting relay 109 (whose circuit was opened as above pointed out by relay 108 at the same time the circuit of relay 110 was closed) has time to deenergize.
- As a further result of the energization of switch-over relay 510 of the switch D', line relay 501 is disconnected from the bridge across conductors 454 and 455, and the bridge including the high resistance relay 507 is substituted therefor. When this occurs, relay 461 at the "A" operator's position deenergizes and opens the circuit of relay 425 at armature 463, whereupon relay 425 deenergizes and disconnects the common calling device conductors and again connects the tip and ring conductors of the cord circuit with the repeating coil windings, causing holding battery to be sent ahead over conductors 454 and 455 to the high resistance relay 507 which energizes to hold up the established connection before the slow acting relay 509 has had time to fall back.
- At the "A" position, relay 461 also opens the circuit of the lamp 466 at armature 465, whereupon the lamp is extinguished to in-

K', opening the circuit of the lamp 711 at 5 springs 709, and opening the circuit of relay 701 at spring 708. Relay 701, upon deenergizing, restores the loop conditions across the conductors 166 and 167 and disconnects 10 battery and ground at armatures 707 and 710, whereupon the differential relay 706 of the switch E, Fig. 2, responds by retracting its armature 138, opening the circuit of line 15 relay 101. This permits the switch to be restored to normal in the usual manner. Relay 106 also restores the loop conditions across the conductors 85 and 86 and removes the battery and ground connections from the 20 loop at armatures 134 and 135. When this occurs, the differential relay 36 in the first selector repeater D, Fig. 1, deenergizes and opens the circuit of release relay 32 at armature 67. Release relay 32 accordingly 25 energizes after the interval for which it is adjusted, resulting in the release of the switch D in the hereinbefore described manner.

In order to explain how calls originating 30 in manual offices and intended for subscribers whose lines terminate in automatic offices are handled, it will be assumed that the subscriber at the manual substation A², Fig. 5, desires to converse with the subscriber at the automatic substation A', Fig. 4. In order to do this the subscriber at substation A² removes his receiver and gets in connection with his "A" operator in the usual manner, after which the "A" operator plugs the 35 call into a trunk leading to the nearest automatic exchange and dials the desired number. In detail, this operation is as follows: When the receiver is removed at substation A² line relay 401 energizes and lights the line lamp 406 at armature 405, whereupon the operator responds by inserting the plug of an idle cord circuit, the plug P of the cord circuit O for example, into the jack J. When this occurs, sleeve relay 402 energizes 40 in series with the supervisory lamp 410 and disconnects the line relay 401, whereupon the said line relay deenergizes and the line lamp 406 is extinguished. Supervisory relay 409 energizes over the calling line and shunts the supervisory lamp 410 to prevent it from becoming lighted at this time.

The operator now throws the key K into listening position and ascertains the wants of the calling subscriber and, upon being informed that he desires to converse with the subscriber at the automatic substation A', tests for an idle automatic trunk by tapping the tip of the plug P' against the sleeve of the jacks, such as J', until an idle one has been found, which condition is manifest by the absence of a click when the contact is made. Assuming that the jack J' is the first one found to be idle, the operator inserts the plug P' therein.

When the plug P' has been fully inserted

into the jack J', a circuit is closed over the tip and ring conductors of the cord circuit and over conductors 441 and 442 for relay 446. Relay 446 thereupon energizes but supervisory relays 421 and 422 in the cord 70 circuit O do not energize on account of the high resistance 456 in the trunk circuit TC. Upon energizing, relay 446 prepares a circuit for relay 445 at armature 453, and at armature 473 grounds sleeve relay 443, whereupon sleeve relay 443 energizes in series with sleeve relay 424 of the cord circuit O; disconnects relay 447 at armature 472; closes a locking circuit for itself and opens its initial circuit at armature 471; and at armature 448 completes a circuit for relay 445. Relay 445, upon energizing, prepares a circuit for relay 444 at armature 452, and at armature 451 locks itself energized independent of relay 446.

In the cord circuit O, sleeve relay 424 energizes in series with the sleeve relay in the trunk circuit and closes a circuit at armature 435 for the calling supervisory lamp 427, whereupon the lamp 427 becomes 90 lighted.

It now remains for the operator to associate her calling device CD with the particular cord circuit in use, and in order to do this, she momentarily operates the push button 426, closing a circuit for relay 425, which thereupon energizes and prepares a locking circuit for itself at armature 437, and at armatures 436 and 438 disconnects the tip and ring conductors from the repeating coil windings and connects them to the closed bridge including the impulse contacts of the calling device CD and the relay 461. When this occurs, relay 446 of the trunk circuit TC deenergizes and completes 105 at armature 453 a circuit through armature 452 for the switch-over relay 444. Relay 444 thereupon energizes and at armatures 449 and 450 disconnects conductors 441 and 442 from relay 446 and extends them to conductors 454 and 455, whereupon the bridged relay 461 at the operator's position energizes over the conductors 454 and 455 and completes at armature 463 the locking circuit through armature 437 for relay 425. The 110 operator may now restore the push button 426, leaving relay 425 locked up. A circuit is now closed for the signal lamp 466 causing the said lamp to become lighted to inform the operator that the calling device is 115 successfully connected through the cord circuit to the trunk.

In the incoming selector repeater D', which switch, it may be stated, is a duplicate of the incoming selector repeater E, Fig. 2, the line and release relays 501 and 502 now energizes and prepare the switch for operation in the usual manner.

The operator now manipulates the calling device CD in accordance with the first digit 120

form the operator that the switch-over operation is completed and that her calling device is free for use in another call.

Since conductor 175, Fig. 4, is now connected to the lower talking conductor 243, the usual busy tone is transmitted back to the calling subscriber. The assumption, however, is that the operator does not have her listening key thrown and therefore will not hear the busy tone. Accordingly, arrangements have been provided for visually informing the operator that the called line is busy. This is accomplished in the following manner: The slow interrupter 176 momentarily applies battery to conductor 175 through the secondary winding of the busy tone transformer at intervals and, upon each application of battery, differential relay 106 in the incoming selector repeater E energizes through the lower line wiper 155 and grounds the lower terminal of relay 107 locally and disconnects it from the lower talking conductor at armature 134, and at armature 135 connects battery through the slow acting relay 109 to the lower trunk conductor 86. Relay 106 also closes a multiple circuit for line relay 101 at armature 138. This latter operation, however, is merely incidental at this time.

In the incoming selector repeater D', Fig. 6, the application of battery to the lower talking conductor 86 by the switch E results in the energization of the differential relay 506 through the lower line wiper and battery is placed on the lower trunk conductor 455, resulting in the energization of relay 422 in the cord circuit O. Relay 422, upon energizing, places a shunt around armature 434 of relay 423 and its resting contact at armature 432, and at armature 433 removes a shunt from around relay 423, whereupon relay 423 energizes in series with sleeve relay 424 and opens a point in the circuit of the lamp 427. It will be noted that due to the novel circuit arrangements employed the above operations have merely resulted in a preparation of the circuits for momentarily extinguishing the lamp 427, but the said lamp has not yet been extinguished. These novel circuit arrangements in the cord circuit O are provided in order to prevent the said lamp 427 from being extinguished prematurely when a call is extended to an operator whose circuits are arranged to place holding battery, in a manner to be pointed out hereinafter, on the calling trunk circuit before she completes the connection. Otherwise this holding battery would prematurely extinguish the lamp 427 and give false answering supervision.

When battery is subsequently removed from conductor 175, Fig. 4, differential relay 106 of the switch E deenergizes; opens the multiple circuit of line relay 101; and restores the bridge across the trunk conductors

85 and 86 to the same condition that existed before it became energized, resulting in the deenergization of the differential relay 506 of the switch D'. Upon deenergizing, relay 506 removes battery from conductor 455, 70 whereupon relay 422 in the cord circuit O deenergizes and opens the circuit of the lamp 427 at armature 432, and at armature 433 replaces the shunt around relay 423. The lamp 427 is accordingly extinguished 75 but is lighted again after a slight interval when the slow acting relay 423 deenergizes and again completes the circuit of the lamp 427 at armature 424. In this way the lamp 427 is momentarily extinguished following 80 each application of battery to the busy signalling circuit, and the operator is informed that the called line is busy.

As above pointed out, the busy tone is transmitted back to the calling subscriber 85 and he replaces his receiver, whereupon relay 409 deenergizes and the lamp 410 becomes lighted. The operator now pulls down the connection, removing the plug P' 90 from the jack J', resulting in the circuit of relay 507 of the switch D' being opened, whereupon relay 507 deenergizes and at its upper armature opens the bridge across the line wipers, at the same time opening the circuit of line relay 501 at its lower armature. 95 The opening of the circuit of line relay 501 results in the release of the switch D' in the usual manner unless it so happens that the plug P' is withdrawn at a time when the differential relay 506 is energized, or is withdrawn just as the differential relay is about to energize, in which case relay 501 does not fall back or, if it does, it is re-operated before release relay 502 has had time to deenergize and the connection is held up until 100 the differential relay 506 deenergizes again. The intervals between successive applications of battery, it may be stated, are long enough to permit the release relays of the various switches involved in the connection, such as release relay 502 of the switch D', 110 and relay 102 of the switch E to deenergize.

Responsive to the opening of the circuit of relay 107 of the incoming selector repeater E, Fig. 2, being opened by relay 507 of the switch D', the switch E is released simultaneously with the release of the switch D' and the switches F, G and H are consequently released in the hereinbefore described manner. 115

It will now be assumed that the line of substation A² is idle when called by the "A" operator as hereinbefore described. In this case no circuit is closed for the busy relay 304 when the wipers of the connector H land upon the called line and the said relay 304 remains deenergized. Accordingly, the deenergization of slow acting relay 305 is followed by the energization of relay 306 with the hereinbefore described results, 125 130

one of which is that the line wipers are connected up and the ringing current is projected out over the called line. Responsive to the line relay 301 being disconnected by release relay 302 whose circuit is opened at armature 339 of relay 306, the usual switch-over operation takes place in the incoming selector repeater E and is followed by the switch-over operation in the switch D', which results in the deenergization of relay 425 in the calling operator's cord circuit O. When this occurs, the circuit including relays 421 and 422 in the cord circuit is bridged across the tip and ring conductors of the plug P' and relay 507 in the selector D' becomes energized to hold up the connection.

When the called subscriber responds and removes his receiver, ring cut-off relay 303 in the connector H is energized in the usual manner and connects the line wipers 341 and 343 with the conductors 241 and 243. When this occurs, relay 105 in the incoming selector repeater E energizes and places a shunt around the high resistance winding of relay 107 at armature 132. Responsive to this operation, relay 505 in the incoming selector repeater D' energizes and shunts the high resistance winding of relay 507, permitting relays 421 and 422 in the cord circuit O to energize. Relay 421 opens the circuit of the lamp 427, giving the operator answering supervision. Relay 422 removes the shunt from around the slow acting relay 423 at armature 433, but this is ineffective at this time in energizing relay 423, owing to the fact that the said relay is simultaneously shunted at armature 430 of relay 421. The calling and called subscribers may now converse with each other in the usual manner and when the conversation is terminated, they replace their receivers. When the receiver is replaced at substation A', relay 105 of the switch E deenergizes and removes the shunt from around the high resistance winding of relay 107, whereupon relay 505 in the switch D' responds by removing the shunt from around the high resistance winding of relay 507, resulting in the deenergization of relays 421 and 422 in the cord circuit O. The lamp 427 is accordingly relighted through armatures 431, 434, and 435.

When the subscriber at substation A² replaces his receiver, the supervisory relay 409 deenergizes and the lamp 410 becomes lighted, and the operator, upon noting the lighted condition of both supervisory lamps, pulls down the connection. The withdrawal of the plug P' from the jack J results in the deenergization of cut-off relay 402.

When the plug P' is removed from the jack J', the bridge across conductors 454 and 455 is opened, permitting relay 507 of the switch D' to deenergize. Also the sleeve contact of the plug breaks contact with the sleeve of the jack, permitting sleeve relay

424 of the cord circuit to deenergize and extinguish the supervisory lamp 427. Sleeve relay 443 of the trunk circuit TC deenergizes also and opens the circuit of relay 445 at armature 448, whereupon relay 445 de- 70 energizes and opens the circuit of relay 444 at armature 452, permitting relay 444 to deenergize also.

In the incoming selector repeater D', Fig. 6, relay 507, upon deenergizing, opens the bridge across the line wipers at its upper armature, permitting relay 107 in the incoming selector repeater E to deenergize and, at its lower armature, opens the circuit of line relay 501, permitting the selector 80 D' to be released in the usual manner. In the incoming selector repeater E, relay 107, upon deenergizing, opens the circuit of line relay 101 at its lower armature 137, permitting this switch, as well as the switches F, G 85 and H, to release in the hereinbefore described manner.

From the above description it will be appreciated that the "A" operator may extend a connection to any automatic line which may be reached by the subscriber at the automatic substation A. It will also be understood that, in case it is desirable, she may extend a connection to any of the various operators who may be called by the subscriber 90 at substation A, for example, the toll recording operator, Fig. 8, or the "B" operator, Fig. 9. A call from the "A" operator's position to the "B" operator's position is extended by the "A" operator in the same manner as has been described in connection with the subscriber at substation A and when the called subscriber, for example, the subscriber at substation A³, responds, the operation of the supervisory relay 804 at the "B" operator's position, results finally in the supervisory lamp 427 at the "A" operator's position being extinguished in the same way that the said supervisory lamp is extinguished when an automatic subscriber responds. 100

In order to explain more fully certain novel arrangements provided in the operator's cord circuit O and the trunk circuit TC to permit the circuits to operate in connection with circuits such as the one extending to the toll recording operator's position, in which holding arrangements are provided to permit the operator to be recalled, it will be assumed that the subscriber at substation A² desires to make a toll call. Accordingly, the subscriber at substation A² removes his receiver and gets the attention of the "A" operator in the usual manner. It will be assumed that the "A" operator uses the cord circuit O to answer the call and that she tests the outgoing automatic trunks and finds the trunk associated with the jack J' to be idle and inserts the plug P' therein. The resulting operations are the same as has been described hereinbefore. When the operator 110 115 120 125 130

connects up and manipulates her calling device CD in accordance with the first digit, the selector D', Fig. 6, raises its wipers opposite the desired level and selects an idle 5 trunk in the usual manner, which trunk, it will be assumed, is the one comprising conductors 85 and 86 and extending to the incoming selector repeater E, Fig. 2.

When the operator manipulates her calling device in accordance with the next digit, 10 the wipers of the switch E are raised opposite the desired level of bank contacts and a trunk extending to the toll recording operator's position, the trunk comprising conductors 186 and 187, for example, is selected. 15 Following this, the switch-over operation takes place in the hereinbefore described manner, resulting in the deenergization of the calling device connecting relay 425 in the 20 operator's cord circuit O, Fig. 5. Responsive to this, relay 507 in the switch D' energizes to hold up the connection.

The toll recording operator is signalled by the lighting of the lamp 711 responsive 25 to the energization of line relay 702, and accordingly throws her answering key K' and her listening key K², whereupon the lamp 711 is extinguished. The toll recording operator now converses with the calling subscriber and makes a notation of his desires, 30 whereupon she restores her listening key K² and directs her attention to other matters.

Assuming that the calling subscriber has finished conversing, he replaces his receiver, 35 whereupon the calling operator receives a steady disconnect from the lamp 410 in addition to the steady glowing of the lamp 427, which lamp is not extinguished responsive to the answering of the toll recording operator, and pulls down the connection, resulting 40 in a disconnect circuit being closed for the lamp 711 at the toll recording operator's position. In this case, as before, battery is automatically placed on the lower talking 45 conductor, upon the deenergization of relay 702, by relay 701. This battery potential operates the differential relay 106 in the incoming selector repeater E and in addition to holding the switch E operated, applies 50 battery to the trunk conductor 86 through the lower left hand repeating coil winding, resulting in the energization of the differential relay 506 in the switch D' which holds the switch D' operated and places battery on conductor 455 through the lower left hand repeating coil winding. The battery potential on conductor 455 operates the grounded relay 447 through the resting contact and armature 472 of the now deenergized sleeve 55 relay 443. Relay 447, upon becoming energized, places a battery potential on the sleeve contact of the jack J' through the high resistance 475, working contact of armature 474 and said armature, resting contact and armature 473, normally closed contacts con-

trolled by armature 471, and sleeve relay 443. This battery potential causes the jack J' and its multiples to test busy to the operators having access to the trunk extending to the switch D'. In this case, the connection is released in the usual manner responsive to the restoration of the key K' by the toll recording operator and relay 447 of the trunk circuit TC deenergizes responsive to the removal of battery from conductor 455 by the differential relay 506 of the switch D'. 70

Assuming now that the calling subscriber at substation A² desires to converse further with the toll recording operator after she has restored her listening key K² as described above, he operates his switch-hook up and down a few times thereby flashing the lamp 410 by means of the supervisory relay 409. This attracts the attention of the "A" operator who responds by throwing her listening key and converses with the calling subscriber. Upon being informed that he desires to converse further with the toll recording operator, the "A" operator momentarily operates the push button 426 a few 90 times, resulting in the energization of relay 425 each time the push button 426 is operated. Upon each operation of relay 425, the tip and ring conductors of the plug P' are disconnected from the battery feed through the repeating coil and are connected to the closed bridge including the holding relay 461. Relay 461 does not energize on account of the fact that no holding current 95 is at this time obtainable over the trunk circuit, and relay 507 in the switch D' deenergizes responsive to the breaking of battery and ground connections away from the trunk by relay 425 of the cord circuit, and opens the circuit of relay 107 of the switch 100 E at its upper armature, whereupon relay 107 deenergizes and opens the circuit of line relay 702, Fig. 8, at armature 136. Line relay 702, upon momentarily deenergizing, momentarily flashes the lamp 711 at armature 705, and at armature 704 causes the holding battery to be sent back over the lower conductor of the trunk to hold the established connection while the relays 507 and 107, Figs. 105 6 and 2, respectively, are deenergized. Each time differential relay 506 of the switch D' places battery on conductor 455, a circuit is prepared for relay 422 of the cord circuit O which is closed as soon as the operator releases the button 426 and allows relay 425 110 to deenergize. Relay 422, upon energizing, removes the shunt from around relay 423 and permits it to energize and, upon subsequently deenergizing, opens the circuit of the lamp 427 at armature 432 and again shunts relay 115 423. Relay 423 deenergizes after a slight interval and again lights the lamp 427. Accordingly, the lamp 427 momentarily flickers responsive to each operation of the button 426 and informs the calling operator 120

125 130

that the re-signalling operation is taking place in the desired manner.

When the toll recording operator again responds, she is able to converse with the calling subscriber as before.

Assuming now that a call to the toll recording operator is made by the subscriber at substation A² in the same manner as above pointed out, except that the toll recording operator has the locking push button 712 operated, relay 701 operates through the left hand contacts of the push button 712 upon the response of the toll recording operator, and places battery on conductor 167, resulting in the holding of the connection independent of the "A" operator and resulting in battery being placed on the conductor 455, Fig. 6, by the differential relay 506. This battery potential operates relay 422 at the cord circuit O which removes the shunt from around relay 423 at armature 433, permitting relay 423 to energize. The lamp 427, however, is not extinguished at this time owing to the fact that armature 434 of relay 423 is shunted at armature 432. The calling subscriber may now converse with the toll recording operator and the disconnect is received by the "A" operator in the usual manner when the calling subscriber replaces his receiver. In case the calling subscriber desires the "A" operator to recall the toll recording operator, he flashes the lamp 410 in the usual manner and the "A" operator flashes the lamp 711 at the toll recording operator's position in the hereinbefore described manner, by operating the button 426. In this case, as before, the lamp 427 of the cord circuit O is flashed responsive to the operations of the push button 426, although in a slightly different manner owing to the fact that battery is at all times present in conductor 455, and relay 422 of the cord circuit is normally energized. Accordingly, the lamp 427 is extinguished responsive to the energization of relay 425 rather than responsive to the removal of battery by the differential relay 506 of the switch D', as it was in the preceding case.

In a system of the type set forth herein, it is sometimes necessary for an operator who receives a call from an automatic exchange to extend the connection automatically and, although the necessity for this may arise in any one of a number of ways, it has been chosen to describe this operation in connection with calls extended to the so-called "zero" operator, which operator, as has been pointed out hereinbefore, is the one who is reached when the number constituting the digit 0 is dialled by a calling subscriber, or by a calling operator, who is having trouble in setting up the desired connection.

The trunks from the tenth level of the

first selector repeaters terminate at the "zero" operator's position in single plug cord circuits, such as the one shown in Fig. 7. This cord circuit is arranged so that calls may be extended either manually or automatically, through the medium of trunk circuits. The trunk circuits through which the calls are extended manually may be of any well known type commonly used in manual telephone systems for trunking from an "A" operator to a "B" operator, and the trunks used in extending calls automatically may be like the one shown in Figs. 5 and 6, extending between the jack J' and the incoming selector repeater D'. 70 75 80

In order to explain more fully certain features pertaining to the circuit arrangements of the "zero" operator's cord circuit O' shown in Fig. 7, and also to bring out more clearly the utility of certain circuit arrangements in the cord circuit O, Fig. 5, it will be assumed that the subscriber at substation A², Fig. 5, desires a connection with an automatic subscriber; that the cord circuit O and the trunk comprising conductors 454 and 455 are used by the "A" operator in attempting to set up the desired connection; and that for some reason she is unable to either complete the connection or to get a busy signal indicating that the desired line is busy, the "A" operator, (after having dialled the desired number) is informed by the continued illumination of the signal lamp 466, Fig. 6, that the connection is being held up at some point and that the switch-over operation has not yet taken place. Accordingly, she removes the plug P' from the jack J', allowing the partly established connection to be released and allowing the circuits to revert to their normal condition. 100 105 The operator may again attempt to establish the desired connection and, assuming that she is again unsuccessful, she again withdraws the plug P' from the jack J' and reinserts it after an interval, with the hereinbefore described results. Assuming that the "A" operator, having other calls that demand her attention, decides to extend the connection to the "zero" operator, she now manipulates her calling device CD in accordance with the digit 0, whereupon the incoming selector repeater D', Fig. 6, raises its wipers to the tenth level and selects an idle trunk, the trunk comprising conductors 87 and 88, for example, and extending to the "zero" operator's position. Since there is no holding battery included in the bridge across conductors 87 and 88 at the "zero" operator's position, the usual change-over operation occurs responsive to the seizure of the above named trunk and the signal lamp 466 at the calling operator's position is accordingly extinguished, indicating that the calling device is now disconnected from the cord circuit O. 110 115 120 125 130

At the "zero" operator's position, line relay 601 of the cord circuit O' now energizes over conductors 87 and 88 and closes at armature 620 a circuit for relay 602. Relay 602 thereupon energizes and closes at armature 623 a circuit for the lamp 610 through armature 632 and its resting contact and the resting contact and armature 636. The lamp 610 accordingly becomes lighted to signal the operator.

The "zero" operator, upon noting the lighted condition of the lamp 610, throws her combined listening and ringing key K⁴ into listening position, thereby connecting up her listening taps to the talking circuit and also closing a circuit for relay 606 which thereupon energizes; closes a locking circuit for itself at armature 631 through armature 621 and its working contact; and at armature 632 extinguishes the lamp 610. The "zero" operator now converses with the calling subscriber and finds out the desired number.

Assuming that the desired number is such that it must be completed automatically, the "zero" operator inserts the plug of the cord circuit O' into a jack, similar to the jack J', Fig. 5, of an automatic trunk, whereupon the relays of the associated trunk circuit operate in the manner described for the relays of the trunk circuit TC, Fig. 5, resulting in a circuit being closed for sleeve relay 608 of the cord circuit, whereupon the said relay 608 energizes and lights the calling supervisory lamp 613 at armature 634.

The operator now operates her push button 614 momentarily, resulting in the calling device connecting relay 609 becoming energized with the hereinbefore described results, and resulting in the energization of the series relay 652 associated with the calling device CD', which closes at armature 654 a locking circuit through armature 638 for relay 609. The "zero" operator now manipulates her calling device CD' in accordance with the digits of the desired number, resulting in the desired connection being established, after which the switch-over operation occurs and relay 609 deenergizes.

When the called subscriber responds, relays 604 and 605 energize and the former opens the circuit of the calling supervisory lamp at armature 626 permitting the said lamp to become extinguished, and at armature 628 shunts the armature 630 of relay 605 and its resting contact so as to prevent the energization of relay 607 at this time. Relay 604 also places a shunt around the high resistance winding of line relay 601 at armature 627, whereupon relays 421 and 422 in the cord circuit O, Fig. 5, energize and the calling supervisory lamp 427 is extinguished.

The calling and called subscriber may now converse with each other as desired.

When the conversation is terminated, the two subscribers replace their receivers, the hanging up of the receiver at substation A² resulting in the lighting of the answering lamp 410 in the cord circuit O, and the hanging up of the receiver at the called substation resulting in the deenergization of relays 604 and 605 in the cord circuit O'. Relay 604 again closes a circuit for the lamp 613 at armature 626, and at armature 627 removes the shunt from around the high resistance winding of relay 601, whereupon relays 421 and 422 in the cord circuit O de-energize and the former closes a circuit for supervisory lamp 427.

The "A" operator, upon noting the lighted condition of the lamps 410 and 427, pulls down the connection, resulting in the circuit of line relay 601 at the "zero" operator's position being opened by relay 507 of the switch D' in the usual manner.

Relay 601, upon deenergizing, opens the circuit of relay 602 which thereupon deenergizes and closes a disconnect circuit for the lamp 610 at armature 623 through the working contact and armature 626, whereupon the lamp 610 becomes lighted. Relay 602 also completes at armature 622 a circuit for relay 602 which includes the working contact and armature 635 of the sleeve relay 608, whereupon relay 603 energizes and grounds locally the lower terminal of line relay 601 and disconnects the said lower terminal from conductor 88 at armature 624, and at armature 625 applies battery through the resistance 611 to conductor 88, resulting in the energization of the differential relay 506 of the switch D', Fig. 6, through its lower winding. Relay 506 now energizes and applies battery to the conductor 455, in addition to closing a holding circuit for line relay 501. Relay 447 in the trunk circuit TC now energizes over conductor 455 and through the resting contact and armature 472 and applies battery through the resistance 475 to the sleeve of the jack J', causing the said jack J' and its multiples to test busy to the operators having access to the trunk. The connection from the "A" operator's position to the "zero" operator's position is accordingly held up until the "zero" operator removes the plug of her cord circuit from the jack. The reason is that, when desired, the "zero" operator may be recalled by the "A" operator who flashes the lamp 610 by momentarily operating the push button 426 a few times when she wishes to recall the "zero" operator, the operation being substantially as described hereinbefore in connection with flashing the toll recording operator by the "A" operator.

When the "zero" operator removes the

plug of her cord circuit from the jack, the connection established through the plug and jack is automatically released in the usual manner; responsive to the deenergization of sleeve relay 608 the lamp 610 is extinguished at armature 636; and the circuit of relay 603 is opened at armature 635, whereupon battery is removed from conductor 88 and the switch D', Fig. 1, releases and relay 477, Fig. 5, deenergizes.

It will be understood that when desired, the locking push button 612 at the "zero" operator's position may be operated, in which case the holding relay 603 energizes through contacts of the push button 612 responsive to the energization of sleeve relay 608, in which case battery is applied to conductor 88 before the established connection is set up, as well as during conversation, resulting in the energization of relay 422 of the cord circuit O (assuming that this cord circuit is used to set up the connection to the "zero" operator's position). Relay 422, however, does not prematurely extinguish the lamp 427 by permitting relay 423 to energize, owing to the fact that it shunts armature 434 and its resting contact at armature 432, as pointed out hereinbefore. In this case, as before, when the called subscriber answers, relays 604 and 605 at the "zero" operator's position energize and the former shunts the high resistance winding of line relay 601, resulting in the energization of relay 505 in the switch D', which relay in turn shunts the high resistance winding of relay 507, permitting relay 421 in the cord circuit O to energize, giving the usual answering supervision. From the above it will be seen that the answering supervision is sent back over the negative talking conductor through the incoming selector repeater D' independent of the holding battery, which is sent back over the positive talking conductor through the said incoming selector repeater D'.

As it may sometimes occur that the "zero" operator calls another operator who may have the holding feature herein described applied to her trunks, the same provision described in connection with the cord circuit O is provided for preventing interference with the supervisory lamp 613 when the holding battery is encountered.

Assuming now that the subscriber at substation A has made several attempts to establish a desired connection and has neither heard the busy signal indicating that the called line is busy nor the ringing tone indicating that the called subscriber's bell is being operated, and that he, accordingly, desires to enlist the aid of the "zero" operator in setting up the connection, and assuming further that the line switch C selects the first selector repeater D when the receiver at substation A is subsequently removed, when the

calling subscriber manipulates his calling device in accordance with the digit 0, the selector D raises its wipers opposite the tenth level and selects an idle trunk, the trunk comprising conductors 87 and 88 for example. Following this, the switch-over operation is performed in the hereinbefore described manner and the lamp 610 is lighted at the "zero" operator's position. The "zero" operator now answers the call in the usual manner by means of her key K⁴ and, upon learning the desired number, proceeds to set up the connection in the usual manner.

In order to explain best a certain feature in the first selector repeater D, it will be assumed that the locking push button 612 is operated when the above call is made. In this case, relay 603 energizes responsive to the energization of sleeve relay 608; places holding battery on conductor 88 at armature 625 and grounds the lower terminal of relay 601 locally; and disconnects it from conductor 88 at armature 624. Accordingly, relays 36 and 37 in the first selector repeater D energize and the former closes at armature 67 a multiple circuit for release relay 32. Relay 37 attempts to close at armature 68 a circuit for relay 38 in order to operate the calling subscriber's meter. This circuit, however, is not completed owing to the fact that armature 68 is attracted.

After the connection has been set up and upon the response of the called subscriber, relays 604 and 605 at the "zero" operator's position energize and the former places a shunt around the upper winding of line relay 601, whereupon the current flow in the upper winding of differential relay 36 in the first selector repeater D and in the lower winding of relay 37 is increased until it approximately equals the current flow in the circuit including the other windings of these relays, the low resistance winding of relay 601, Fig. 7, having a resistance approximately the same as the resistance 611. Accordingly, relay 37 is now energized through both its windings and differential relay 36 deenergizes and retracts its armature 67, opening the multiple circuit of release relay 32 and closing a circuit through armature 68 and its working contact for relay 38. Relay 38 thereupon energizes and closes a locking circuit for itself at armature 71, and at armature 69 closes the previously traced circuit for the magnet of the meter M, causing the number wheels of the meter to be advanced to register the call.

It would appear now that, since differential relay 36 has deenergized and opened the multiple circuit of relay 32, the switch D will release when the receiver at substation A is replaced, regardless of the holding battery on the lower trunk conductor. This, however, is not the case, because when the line relay 31 deenergizes it opens the circuit of

the upper winding of differential relay 36 and of the lower winding of relay 37 at armature 51. Differential relay 36 accordingly energizes and again closes a holding circuit for relay 32 at armature 67, and relay 601 at the "zero" operator's position de-energizes and gives her a disconnect signal.

The connection is released in the usual manner when the "zero" operator withdraws the plug or is held up by the "zero" operator in case the calling subscriber operates his switch-hook up and down.

Brief consideration will now be given to the arrangements provided at each of the 15 selectors and at each of the selector repeaters for giving both a visual and an audible busy signal in case all the trunks in a selected group test busy. Considering first the selector G, Fig. 3, in case all the 20 trunks in the selected level are busy, the said selector is not able to select any of the trunks and the rotary movement continues until the wipers 236-238, inclusive, have passed beyond the last trunk or, in 25 other words, until the eleventh rotary step has been taken, it being assumed that the switch has ten sets of bank contacts in each level. When the above situation is met with, the contacts indicated on the drawings as the eleventh rotary step contacts 30 are closed, as indicated, by a cam carried by the switch shaft, and the busy lead 175 is connected by these contacts to the wiper 238. At the same time, test wiper 237 35 passes off the last bank contact and switching relay 253 accordingly energizes, connecting the trunk to the line wipers and disconnecting line relay 251. This causes the hereinbefore described switch-over operation to take place, connecting up the talking circuit back to the calling subscriber. Accordingly, the busy tone from the conductor 175 is transmitted back to the calling subscriber to inform him that 40 the desired connection can not be completed at this time. Due to the operation of the slow interrupter 176 hereinbefore explained, a flashing signal is displayed at the calling operator's position in case the 45 call comes through an operator's position. The same operation takes place when any of the other selectors or selector repeaters 50 is unable to find an idle trunk.

The operation of the various switches 55 and other circuits having been explained in detail, a few remarks will be directed to the lay-out of the trunking in a system of this sort. Considering first the incoming selector repeater E, Fig. 2, which, as 60 pointed out before, is an office selector, this switch has access on levels other than those shown to trunks leading to the other automatic offices in the same district. Each of these trunks terminates at the distant end

in an incoming selector repeater identical 65 with the incoming selector E.

The position of these latter switches, however, from a trunking standpoint, is that of thousands selectors and they have access along with the local thousands 70 selectors to hundreds selectors corresponding to the selector G, Fig. 10. From the above, it naturally follows that the banks of the thousands selector F, Fig. 3, are multiplied 75 with the banks of the incoming thousands selectors which handle the traffic directed to this office from other offices in the same district.

Considering now the first selector repeater D, Fig. 1, and the incoming switch 80 D', Fig. 6, whose functions from a trunking standpoint are those of thousands selectors, these switches have access on each level other than the tenth to a group of trunks leading to a separate district. With 85 the sole exception of the trunks leading to the local district, each of these trunks extends to and terminates in an incoming selector repeater, used as an office selector, such as the incoming selector repeater E, 90 Fig. 2. On the level leading to the local district, however, each of the trunks extends to and terminates in a local office selector whose function from a trunking standpoint is identical with that of the 95 switch E, Fig. 2, and whose circuits are identical with those of the selector F or the selector G, Fig. 3. The banks of these local office selectors are multiplied together and the trunks are taken from the various levels 100 to each of the offices in the local district. Each of these latter trunks, with the sole exception of the trunks local to the calling office, extends to and terminates in an incoming selector repeater identical with the 105 switch E, Fig. 2, whose function from a trunking standpoint is that of a thousands selector like the thousands selector F, Fig. 3. On the local level, however, each of the 110 trunks extends to and terminates in a local thousands selector identical with the selector F, Fig. 3.

From this it may be seen that the selectors D and D' feed talking battery to calling and called subscribers on local calls 115 on account of the fact that no intermediate selector repeaters are at such times encountered.

What is claimed is:

1. In a telephone system, a first directively controlled automatic switch, a second directively controlled automatic switch, means for setting up a connection from a calling to a called subscriber, said connection including said switches in serial relation, a calling bridge in the first switch used during the establishment of the connection to control the second switch, a talking bridge in 120 125

said first switch used during conversation to supply talking battery to the called line through said second switch, a change-over means in said first switch, and means in the second switch for operating said change-over means to open said calling bridge and to close said talking bridge, the last named means operating whenever the mechanical operation of the second switch is completed.

2. In a telephone system, a first directly controlled automatic switch, a second directly controlled automatic switch, means for setting up a connection from a calling to a called subscriber, said connection including said switches in serial relation, a calling bridge in the first switch used during the establishment of the connection to control the second switch, a talking bridge in said first switch used during conversation to supply talking battery to the called line through said second switch, a change-over means in said first switch, and means in the second switch for operating said change-over means to open said calling bridge and to close said talking bridge, the last named means operating responsive to a busy condition on the called line.

3. In a telephone system, a first directly controlled automatic switch, a second directly controlled automatic switch, means for setting up a connection from a calling to a called subscriber, said connection including said switches in serial relation, a calling bridge in the first switch, a line relay in said second switch controlled over said calling bridge for controlling said second switch during the establishment of the connection, a talking bridge in said first switch used during conversation to supply talking battery to the called line through said second switch, means operative upon the termination of the operation of said second switch for disconnecting said line relay, and a change-over means in said first switch responsive to the disconnection of said line relay to open said calling bridge and to close said talking bridge.

4. In a telephone system, an automatic switch having a line relay, a slow acting change-over relay, a primary magnet, and a secondary magnet, means for energizing said line relay to close a circuit to energize said change-over relay, means controlled by said change-over relay to prepare a circuit for said primary magnet, means for momentarily deenergizing said line relay one or more times, means responsive to each of said deenergizations for closing said prepared circuit to operate the primary magnet, means responsive to the first energization of said primary magnet for shifting the circuit of said change-over relay so that it is subsequently closed only on the deenergization of said line relay, whereby said change-over relay is maintained operated during

the series of primary magnet operations and falls back at the end thereof, and means responsive to the deenergization of said change-over relay for initiating the operation of said secondary magnet.

5. In a telephone system, an automatic switch having primary and secondary magnets, an operating conductor, a change-over relay, means for closing a circuit for said relay responsive to a seizure of said switch to connect said operating conductor to said primary magnet, means for sending one or more impulses of current over said operating conductor to operate said primary magnet, means for closing a second circuit for said relay and for opening its first circuit upon the first impulse of current, and means for opening said second circuit at the end of said impulses to deenergize said relay to disconnect said operating conductor from said primary magnet and connect it to said secondary magnet.

6. In a telephone system, an automatic switch having primary and secondary magnets, an operating conductor, a change-over relay, means for energizing said change-over relay to close a point in the circuit of said primary magnet and for subsequently deenergizing said change-over relay to close a point in the circuit of said secondary magnet, a called line, means including said switch for extending a connection to said called line and for applying ringing current to said line, and means controlled by a response on the called line for energizing said change-over relay to disconnect said ringing current therefrom and to close a talking connection.

7. In a telephone system, a trunk divided into two sections telephonically disconnected from each other, means including said trunk and a train of automatic switches for extending a connection to a called line, and means controlled by one of said switches and located in one of the previously engaged switches for telephonically connecting the two sections of said trunk subsequent to the operation of the controlling switch.

8. In a telephone system, first and second automatic switches, a switch-over relay in each, a line relay and a holding relay in said second switch, means including said switches in serial relation for extending a connection to a called line, said second switch being operated from said first switch through the medium of said line relay, means operative after the connection is set up and before the response on the called line occurs for operating the switch-over relay in the second switch to substitute said holding relay for said line relay, and means responsive to said substitution for operating the switch-over relay in the first switch.

9. In a telephone system, a trunk terminating in a selector, a second trunk terminat-

- ing in a connector, means for operating the selector to unite said trunks, a bridge across the talking conductors of the connector trunk including a line relay and battery connections for supplying current, a bridge across the selector trunk for energizing said line relay, means for interrupting the line relay circuit to operate the connector to connect with a called line, means responsive to the completion of the connection for opening said first bridge, and means in the selector responsive to the opening of said first bridge for introducing a source of current in said second bridge to supply talking current to the called line. 15
10. In a telephone system, a trunk terminating in a selector, a second trunk terminating in a connector, means for operating the selector to unite said trunks, a bridge across the talking conductors of the connector trunk including a line relay and battery connections for supplying current, a bridge across the selector trunk for energizing said line relay, means for intermittently opening said second bridge to interrupt the line relay circuit in accordance with the last two digits in a called number to operate said connector to connect with a called line, means operated automatically at the end of the final digit 20 for opening said first bridge, and a relay in the selector responsive to the opening of said first bridge for introducing a source of current in the second bridge to supply talking current to the called line. 25
- 30 11. In a telephone system, a connector switch, a temporarily established talking circuit extending from a calling line to said connector, inductive connections dividing said circuit into two sections, a selector included in the second section, means for controlling said connector over the two talking conductors of the second section in series to connect with a called line, a bridge at said connector for supplying current to said second section while the connector is being operated, means for opening said bridge when the called line is connected with, and means at the junction of said sections responsive to the opening of said bridge for supplying current to said second section to provide talking current to the called station when the called party answers. 35
- 40 12. In a telephone system, a train of switches including a selector and a final connector for connecting a calling and a called line, a common talking and operating circuit extending through said switches, a bridge at said connector for supplying current to said circuit while the connector is being operated, a second bridge for supplying current to said circuit for talking at a point ahead of said selector, and means including a relay energized over said circuit by current from the connector for maintaining said second bridge 45
- 50 open until the operation of the connector is completed. 65
13. In a telephone system, a train of switches including a selector and a final connector for connecting a calling and a called line, a common talking and operating circuit extending through said switches, a bridge at said connector for supplying current to said circuit while the connector is being operated, a second bridge for supplying current to said circuit after the connector is operated at a point ahead of said selector, the current supplied from said point energizing the transmitter at the connected called line, means for opening said first bridge before the called party answers, and a relay responsive to the opening of said first bridge for closing said second bridge. 70 75
- 80 14. In a telephone system, means including a selector repeater and a final connector for extending a connection to a called line, a trunk extending between said switches including two talking conductors, a circuit for controlling the operation of said connector including the wipers of said selector repeater and said talking conductors in series, a circuit for supplying talking current to the connected called line also including said wipers and talking conductors in series, means associated with said connector for supplying current to said first circuit, means associated with said selector repeater for supplying current to said second circuit, means responsive to the completion of the operation of said connector for disconnecting the source of current supply from said first circuit, and means responsive to cessation of current flow in said first circuit for rendering effective the said current supplying means in said selector repeater. 85 90 95
- 100 15. In a telephone system, a temporarily established trunk connection including two talking conductors, two bridges across said conductors at one end thereof, the first being open and the second closed, a relay in the second bridge and a source of current in the first bridge, a closed bridge at the distant end of said conductors including a relay and a source of current, said second relay being energized over a circuit including said two conductors and the second bridge in series, means associated with said second bridge for repeatedly opening the circuit of said second relay to intermittently operate the same, a connector switch controlled by said second relay to extend said talking conductors to a called line, means associated with the said connector for again opening said circuit when the connector completes its operation, said first relay being responsive to such circuit opening, and means controlled by said first relay for opening said second bridge and closing said first bridge. 105 110 115
- 120 16. In a telephone system, trunk lines, a

- selector repeater operable to select and connect with an idle one of said trunk lines, means in said selector repeater for closing a bridge across the selected trunk line, a series of automatic switches responsive to series of interruptions in said bridge to extend the selected trunk line to a called line, a switching relay in said selector repeater for introducing a source of current in said bridge, 10 a second relay included in the bridge for preventing the operation of said switching relay, means in each of said series of switches for supplying current to said second relay to maintain the same energized 15 during the establishment of the connection, and means in the final switch for interrupting the current supply to deenergize said second relay and permit the energization of said switching relay.
17. In a telephone system, an impulse repeater for producing a series of interruptions in the current flow through a closed loop, means outside of said repeater for opening said closed loop, a switch-over relay 20 in said repeater operative responsive to said opening of the closed loop, and a slow acting relay in said repeater energized during the production of the series of interruptions in the closed loop to prevent the said operation of said switch-over relay from taking place.
18. In a telephone system, an impulse repeater having two talking conductors and a control relay energized in a closed bridge 25 across the said talking conductors, a repeating relay and means to operate it to produce a series of interruptions in the said bridge, a switch-over relay operated responsive to a deenergization of said control relay, and a slow acting relay energized during said series 30 of interruptions to prevent said switch-over relay from operating when the control relay deenergizes responsive to the series of interruptions.
19. In a telephone system, a connector switch having two talking conductors and a line relay included in a bridge across them, a release relay and a circuit for energizing it through contacts on the line relay, 35 contacts on the release relay for closing a locking circuit for itself independent of the line relay contacts, means controlled by the said line relay when it is operated over the said talking conductors to operate the switch to extend a connection to a desired line, off normal contacts opened when said operation starts to open a point in the bridge across the talking conductors, contacts on said release relay bridging said off normal contacts as long as said release relay is energized, and relay contacts operated subsequent to the completion of the said operation of the switch to open the locking circuit of the said release relay, whereby the 40 release relay is deenergized to disconnect the line relay from in bridge of the talking conductors.
20. In a connector switch, two line conductors, a line relay bridged across said line conductors through off normal contacts of the switch, a release relay energized when the switch is seized, contacts on the release relay for shunting the said off normal contacts when the relay is energized, means controlled by the line relay when it is operated over the said talking conductors to set the switch onto a desired called line, and means operated responsive to the said setting of the switch to bring about the deenergization of said release relay to disconnect said line relay from in bridge of the talking conductors.
21. In an automatic telephone system, an automatic switch having a control relay energized in a closed control circuit, a second relay energized in a local circuit, means outside the switch to produce interruptions in said control circuit, means controlled by said line relay when it responds to the said interruptions to operate said switch to extend a connection to a desired called line, off-normal contacts on said switch for opening a point in the said control circuit, contacts on said second relay closed when the relay is energized for shunting said off normal contacts, and means effective upon the completion of the operation of said switch to open said local circuit, whereby said second relay is deenergized to open said control circuit.
22. In a telephone system, a connector switch having a line relay and a circuit for energizing it, a release relay and a circuit for energizing it through contacts on the line relay, means controlled by the line relay through contacts on the release relay for operating the switch, off-normal contacts on the switch for opening the circuit of the line relay, and contacts on the release relay shunting the said off-normal contacts.
23. In a telephone system, a connector switch having a release magnet and a release relay for controlling the circuit of said magnet, means for operating said switch to extend a connection to a desired called line, a busy relay energized in case said line is busy, a switching relay energized in case said line is idle, and contacts on said switching relay and said busy relay in series for opening the circuit of said release relay whether the called line is busy or idle.
24. In a telephone system, a connector switch having a release magnet and a release relay for controlling the circuit of said magnet, means for operating said switch to extend a connection to a desired called line, a busy relay energized in case said line is busy, contacts on said busy relay for opening the circuit of said release relay and release magnet, and a slow acting relay energized to disconnect the line relay from in bridge of the talking conductors.

gized during the operation of the switch having contacts for shunting the said contacts on the busy relay.

25. In a telephone system, a connector switch having a release magnet and a release relay for controlling the circuit of said magnet, means for operating said switch to extend a connection to a desired called line, a busy relay energized in case the called line is busy to connect a busy signalling tone to the calling line, and contacts on said busy relay for opening the circuit of said release relay and said release magnet.

26. In a telephone system, a connector switch having a release relay energized when the switch is seized, means for operating the switch to extend a connection to a desired called line, a busy relay energized responsive to a busy condition of the called line, contacts on the busy relay for opening the circuit of the said release relay, and a circuit for applying a busy signalling current to a calling line including working contacts on the busy relay and resting contacts on the said release relay.

27. In a telephone system, an automatic switch having a release trunk conductor grounded at a point outside of the switch, a line relay for the switch, a release relay having a circuit closed through working contacts of the line relay from a local source of ground potential over a local conductor, contacts on said release relay for disconnecting said local conductor from said local source of ground potential and for connecting it to said release trunk conductor, an operating magnet for the switch energized through working contacts on the release relay and resting contacts on the line relay, off normal contacts operated when the switch goes off normal to disconnect the release relay from the working contacts of the line relay and to connect it in a circuit through the resting contacts of the line relay, means for removing the ground potential from the release trunk conductor to bring about the deenergization of the release relay, whereby said release relay restores the said local conductor to the local source of ground potential, and a circuit for the release magnet including said local source of ground potential and the said local conductor as well as resting contacts on the said release relay.

28. In a telephone system, an automatic switch having a release trunk conductor grounded at a point outside the switch, a release magnet for said switch, a release relay energized over said release trunk conductor and through a local conductor, means for deenergizing said release relay by removing the said external ground connection from the said release trunk conductor, contacts on said release relay closed when it deenergizes to disconnect said local conductor from itself and to connect it to

said release magnet instead, and other contacts on said release relay for disconnecting said local conductor from the said release trunk conductor and for connecting it to a local source of ground potential to energize 70 said release magnet.

29. In a telephone system, a connector switch, an operating conductor in said switch, primary and secondary magnets for said switch, a change-over relay, means for seizing said switch and for energizing said change-over relay through off normal contacts of the switch to disconnect said operating conductor from the secondary magnet and to connect it to the primary magnet instead, means for sending a series of impulses over said operating conductor to the primary magnet, and a slow acting relay energized over said operating conductor to close a locking circuit for said change-over relay 80 independent of said off-normal contacts, whereby said change-over relay is maintained operated throughout the primary movement and falls back at the end of the primary movement to disconnect the operating conductor from the primary magnet and to connect it to the secondary magnet again.

30. In a telephone system, calling and called lines, means for setting up a connection between said lines, a supervisory device, means for operating said device upon the response of the called subscriber, and means controlled over a circuit including one line conductor and excluding the other for intermittently operating said device when 95 said circuit is intermittently closed, said device being non-responsive to a continuous closure of said circuit.

31. In a telephone system, an operator's switchboard, a trunk extending from said switchboard to an automatic switch, a cord circuit at said switchboard divided into two sections, means for connecting said cord circuit with said trunk, a calling device, a calling-device-connecting relay, operator-controlled means for operating said relay to disconnect the two sections of said cord circuit from each other and to connect the second section with said calling device, a holding relay energized over said trunk for 105 closing a locking circuit for said calling-device-connecting relay responsive to the operation of the latter, means controlled by said calling device for setting up a desired connection, and means effective upon the 110 termination of the last operation of the said calling device for deenergizing said holding relay to open the locking circuit of said connecting relay.

32. In a telephone system, an operator's 125 switchboard, a trunk extending from said switchboard to an automatic switch, a cord circuit at said switchboard divided into two sections, means for connecting said cord circuit with said trunk, a calling device, a call- 130

- ing-device-connecting relay, operator controlled means for operating said relay to disconnect the two sections of said cord circuit from each other and to connect the 5 second section with said calling device, a holding relay energized over said trunk for closing a locking circuit for said calling-device-connecting relay responsive to the operation of the latter, means controlled by 10 said calling device for setting up a desired connection, means effective upon the termination of the last operation of the said calling device for deenergizing said holding relay to open the locking circuit of said 15 connecting relay, a signal device individual to said calling device, and means for operating said signal device to indicate whether or not said calling device is connected with said cord circuit.
- 20 33. In a telephone system, an operator's switchboard, a trunk extending from said switchboard to an automatic switch, a line relay and a source of current in series bridged across said trunk at said automatic switch, said trunk being divided into two sections, a cord circuit at said position, a source of current bridged across the conductors of said cord circuit, means for uniting the conductors of said cord circuit with 25 the conductors of the first section of said trunk, a calling device, means for disconnecting said source of current from said cord circuit and for connecting said calling device with said cord circuit, and means responsive to the operation of said last means for uniting the two sections of said trunk.
34. In a telephone system, a meter, an automatic switch, a trunk, means including said switch and said trunk for setting up a 40 connection to a called line, two relays in said switch, means controlled over one talking conductor of said trunk independent of the other for energizing said relays in series to close a holding circuit for said switch, and means controlled over the other talking conductor independent of the first for deenergizing only one of said relays to open said holding circuit and to operate said meter.
- 45 35. In a telephone system, a trunk line, means for producing a flow of direct current thereover, automatic switching mechanism, means for sending impulses over said trunk line to operate said mechanism to set up a telephone connection by interrupting the 50 current flow over said trunk line, means responsive to the setting up of said connection for substantially reducing the current flow over said trunk line, a bridge across the conductors of the said trunk line through which said current flow takes place, and means responsive to the reduction of current flow for altering said bridge.
- 60 36. In a telephone system, a trunk line, means for producing a flow of direct current thereover, automatic switching mechanism,
- means for sending impulses over said trunk line to operate said mechanism to set up a telephone connection by interrupting the current flow over said trunk line, a bridge across the conductors of the said trunk line through which said current flow takes place, and means responsive to the reduction of current flow for altering said bridge.
- 65 37. In a telephone system, a trunk line having a flow of direct current thereover, automatic switching mechanism, means for sending impulses over said trunk to operate said mechanism to set up a telephone connection by interrupting the current flow over said trunk line, means responsive to the setting up of said connection for substantially reducing the current flow over said trunk line, a second bridge, and means responsive to said reduction for disconnecting the first bridge from across the said trunk line and for connecting the second bridge across said 70 trunk line.
- 75 38. In a telephone system, a trunk line divided into two sections, a train of automatic switches controlled over the second section to extend a telephone connection, and means in said trunk line responsive to the operation of the last switch in said train for uniting the two sections of the trunk line.
- 80 39. In a telephone system, a trunk line comprising two disconnected sections, a repeater arranged to repeat into the second section impulses received over the first section, a train of automatic switches responsive to the repeated impulses for setting up a telephone connection to a called line, and means in said trunk line revertively controlled over the established connection prior to a response on the called line for telephonically connecting the two sections of said trunk line.
- 85 40. In a telephone system, a trunk line comprising two disconnected sections, a repeater arranged to repeat into the second section impulses received over the first section, a train of automatic switches responsive to the repeated impulses for setting up a telephone connection to a called line, and means in said trunk line revertively controlled over the established connection prior to a response on the called line for conductively connecting the two sections of said 90 trunk line.
- 95 41. In a telephone system, a trunk line comprising two telephonically disconnected sections, a repeater arranged to repeat into the second section impulses received over the first section, a train of automatic switches responsive to the repeated impulses for setting up a telephone connection to a called line, and means in said trunk line revertively controlled over the established connection

prior to a response to the called line for telephonically connecting the two sections of said trunk line.

42. In a telephone system, a trunk line comprising two disconnected sections, a repeater arranged to repeat into the second section impulses received over the first section, a train of automatic switches responsive to the repeated impulses for setting up a telephone connection to a called line, and means in said trunk line revertively controlled over the established connection prior to a response on the called line for inductively connecting the two sections of said trunk line.

43. In a telephone system, a trunk line comprising two disconnected sections, a train of automatic switches responsive to impulses for setting up a telephone connection to a called line, and means in said trunk line revertively controlled over the established connection prior to a response on the called line for telephonically uniting the two sections of said trunk line.

44. In a telephone system, a trunk line, means for setting up a connection through said trunk line from a calling line to a called line, means for setting up over the established connection an unbalanced current flow in the two conductors of the trunk line in order to maintain the connection established, and means controlled by a response from the called line for balancing the current flow over the two conductors of the trunk line in order to indicate the response.

45. In a telephone system, means for setting up a telephone connection including two automatic switches in serial relation, said connection including two talking conductors extending between said switches, means responsive to current flow in a circuit including one conductor for maintaining the first switch operated, and means responsive to current flow in a separate circuit including the other conductor for maintaining the second switch operated.

46. In a telephone system, means for setting up a telephone connection including two automatic switches in serial relation, said connection including two talking conductors extending between said switches, means responsive to current flow in a circuit including one conductor for maintaining the first switch operated, means responsive to current flow in a separate circuit including the other conductor for maintaining the second switch operated, and means responsive to an increase in the current flow over the first named circuit for assessing a charge against the calling subscriber.

47. In a telephone system, means for setting up a telephone connection through an automatic switch in an automatic exchange to a manual switchboard, means responsive to current flow over one talking conductor

of the connection for controlling call and disconnect supervision at said switchboard, means responsive to an increased current flow over said circuit brought about by means at said switchboard for registering in the automatic exchange the operation of the means at the manual switchboard, and means responsive to current flow in a separate circuit over the other talking conductor of the established connection for controlling the release of said automatic switch.

48. In a telephone system, an automatic switch, a trunk line, means for setting up a telephone connection through said switch to said trunk line, a manual switch board having supervisory apparatus, a second automatic switch, means for further extending said connection to include said switchboard or said second switch, alternatively, means controlled by current flow over a talking conductor of said trunk line for controlling the supervisory apparatus at said manual switchboard in case such switchboard is included in the connection and for controlling the release of the second automatic switch in case said switch is included in the connection in place of said switchboard, means at the called end of said connection in either case for increasing the current flow over said conductor to indicate that a response has been obtained, and means at the calling end of the connection responsive to such increase in current flow for registering the response.

49. In a telephone system, a trunk line, an automatic switch, a manual switchboard, means for extending a connection over said trunk line and through either said switchboard or through said switch, supervisory apparatus at said switchboard controlled by current flow over said trunk line in one case and switch-holding means at said switch controlled by such current flow in the other case, means at the called end of the connection in either case for increasing the current flow over said trunk line to indicate that a response has been obtained, and means at the calling end of the connection responsive to such increase for indicating the obtained response.

50. In a combined automatic and manual telephone system, a trunk line, means including an automatic switch for setting up a connection to said trunk line from an automatic substation, means including a manual switchboard for setting up a connection to said trunk line from a manual substation, means for completing either of said connections over said trunk line and for setting up a current flow over said trunk line, means controlled from the called end of the connection for increasing the current flow over said trunk line when a response is obtained, registering means responsive to such increase in case the connection has been set up from said automatic substation, and a super-

- visory device similarly responsive for indicating a responded condition at said switchboard in case the connection has been set up from said manual substation.
51. In a telephone system, means including an automatic switch for setting up a connection through a trunk line comprising two talking conductors, a holding relay connected during conversation between one talking conductor of the trunk line and ground, circuit arrangements for energizing said relay by current flow over the associated conductor of the trunk line, while there is no current flow over the other conductor, and circuit arrangements controlled by said relay for holding said automatic switch operated when the relay is operated.
52. In a telephone system, means including an automatic switch and a trunk line seized by said switch for setting up a telephone connection, said trunk line including two talking conductors, a holding circuit for said automatic switch, and means whereby said holding circuit is effective in case the current flow over one of said talking conductors is substantially greater than the current flow over the other and ineffective in case the current flow is substantially equal over the two talking conductors.
53. In a telephone system, means including a two conductor trunk line for setting up a telephone connection, means for transmitting forward over one conductor of said trunk line a holding and supervisory indication, means for transmitting back over the same conductor a supervisory indication co-existent with said holding indication, and means for transmitting back over the other conductor of said connection a holding indication, all said indications depending upon a continuous flow of direct current.
54. In a telephone system, a trunk line divided into two sections, a bridge across each section, a source of direct current included in the bridge across the second section, means for setting up a telephone connection including both sections of said trunk line, and means responsive automatically upon the completion of said connection for shifting said current source from the first bridge to the second bridge.
55. In a telephone system, two trunk lines, each trunk line comprising two sections, a bridge across the second section of the first trunk line, a bridge across the first section of the second trunk line including a source of direct current, a bridge across the second section of the second trunk line, means for setting up a telephone connection through both sections of the first trunk line and subsequently through both sections of the second trunk line to a called line, means automatically responsive to the completion of the connection to the called line for shifting the source of direct current from the bridge across the first section of the second trunk line to the bridge across the second section of the second trunk line in order to energize the transmitter on the called line when the called subscriber responds, and means responsive to the removal of the current source from the bridge across the first section of the second trunk line for inserting a source of direct current in the bridge across the second section of the first trunk line.
56. In a multi-office telephone system, a first selector repeater, an incoming selector repeater in a distant office, a final connector in said distant office, means for setting up a telephone connection from the first office through said first selector repeater over an interoffice trunk line to the incoming selector repeater and thence through said connector to a called line, a back-bridge connection in the first selector repeater controlled by the line relay of such selector repeater, a front-bridge connection in said incoming selector repeater including a source of current, a back-bridge connection in said incoming selector repeater, a line relay bridge across the talking conductors at said connector including a source of current, means effective upon the completion of the setting of said connector for disconnecting its line relay bridge, means, said incoming repeater responsive thereto for shifting the current source from its front bridge to its back bridge in order to supply talking current for energizing the transmitter on the called line when the called subscriber responds, and means in said first selector repeater responsive to said shifting operation for inserting a source of current in its back bridge in order to hold the incoming selector repeater and the connector operated under the control of the line relay of the first selector repeater.
57. In a combined automatic and manual telephone system, a trunk line, switching mechanism for setting up a connection from a calling automatic line to said trunk line, operator-controlled switching mechanism for setting up a connection from a manual calling line to said trunk line, an automatic switch, means for setting up a current flow over said trunk line and for interrupting said current flow to operate said automatic switch to further extend the connection, means responsive to the complete extension of said connection for materially reducing the current flow in said trunk line, while permitting sufficient current flow to take place over the trunk line to hold said automatic switch in an operated position, means controlled from the called end of the connection for increasing the current flow over said trunk line when a response is obtained, registering means associated with the said automatic line and responsive to said increase in case the connection has been set

up from said automatic line, and operator's supervisory apparatus similarly responsive for indicating a responded condition in case the connection has been set up from said 5 manual line.

58. In an automatic telephone system in which setting and supervision are effected over the talking conductors under different circuit conditions, means for switching over 10 from setting conditions to supervisory conditions responsive to the completion of the connection in one case, and for performing an identical switch-over operation responsive to the encountering of a busy trunk group 15 in another case.

59. In an automatic telephone system in which the setting up of a connection through successive switching stages and supervision are effected over the talking conductors under 20 different circuit conditions, means for

switching over from setting conditions to supervisory conditions responsive to a busy condition encountered at any one of a plurality of switching stages.

60. In an automatic telephone system in 25 which current for the purpose of controlling the setting of switches is sent back over the two talking conductors in series during the process of setting up the connection, means for suitably altering the circuit connections so that current for speaking and holding purposes is transmitted forward over the same conductors thereafter, said altering means being arranged to perform 30 said alteration responsive to a cessation of 35 the said setting-control current.

In witness whereof, I hereunto subscribe my name this 12th day of December, A. D., 1923.

JOHN WICKS.
